UNITED STATES PATENT OFFICE

2,297,743

PAPER FEEDING DEVICE

Fred M. Carroll and Derk J. Oldenboom, Binghamton, N. Y., assignors to International Business Machines Corp., New York, N. Y., a corporation of New York

Application August 22, 1936, Serial No. 97,372

21 Claims. (Cl. 235—61.7)

This invention relates generally to paper feeding devices and more specifically to ledger posting printing structures in a perforated record controlled tabulator.

An object of the invention is to provide an improved form of ledger posting sheet positioning and printing means. A perforation is punched in the margin of the ledger sheet for each line of print impressed on the sheet, so that the sheet may be removed after printing to be reinserted at a later time and automatically positioned for printing directly under the last line of print, the perforations controlling the feeding and stopping of the sheet.

An object of the invention is to provide electrical devices for sensing the marginal perforations in the ledger sheet and thereby controlling the feeding and positioning of the sheet.

A feature of the invention is the provision of a high speed feeding mechanism in addition to a line spacing feeding mechanism, both under control of the electrical perforation sensing devices. Time is saved by the action of the high speed mechanism which feeds the previously printed section of the ledger sheet past the printing position at a fast rate. As the sheet approaches the new printing position, the high speed mechanism is automatically disengaged and the line spacing mechanism is engaged to feed the sheet in accurate registration to the new line. The high speed feed mechanism is also used to eject a printed sheet after posting under control of the listing or tabulating mechanism.

A platen detent is controlled along with the high speed feed so that when the platen is driven at a rapid speed the detent is disengaged.

It is an object of the invention to provide the electrical marginal perforation sensing devices with a plurality of brushes for diversified control. Three brushes are provided; the one brush maintains high speed feeding as long as perforations are sensed, then, as the last perforation passes the high speed brush in nearing the printing position, the second brush comes into effect to control line spacing to feed a line for each of the last few perforations and one line below the last posting entry, and finally, when the end of the sheet is reached, this condition is sensed by a third brush which controls ejection of the sheet and lifting of the platen for the insertion of a new sheet.

Another object of the invention is to provide a common unit containing the ledger sheet sensing and punching devices. The unit is automatically shifted so that either the sensing device or the

punching device cooperates with the same marginal area of the ledger sheet. When the ledger sheet is entered and fed to the proper position, the sensing brushes are located in alignment with

5 the marginal perforations to control feeding, then, as soon as printing is initiated, the brush and punch unit frame is shifted so that the punch is in alignment with the marginal perforations to punch a hole as an indice for each line of print.

10 It is an object of the invention to provide means for sensing the end of a sheet and mechanism controlled thereby for automatically lifting a platen into sheet receiving position after the printed sheet is ejected. As the platen is lifted other mechanisms are automatically brought into play to separate feed rollers so that another ledger may be inserted to pass therebetween and stop in a correct starting position against end stops which automatically protrude as the platen lifts.

15 Another object of the invention is to provide key controlled devices for automatically swinging the platen and sheet down into printing position. As the platen nears the printing position the end stops automatically move out of the way.

20 25 The feed rollers move into contact with the sheet to space it under posting control. The rollers grip the paper immediately upon depression of the swing control key.

20 It is an object of the invention to provide means 25 for automatically spacing a ledger sheet past a top heading space when the platen is automatically lowered from sheet receiving position to printing position.

25 A feature of the invention is the provision of interlocking controls between the ledger posting carriage and a record controlled printing tabulator of the kind disclosed in U. S. Patent No. 1,976,617. Devices are provided to prevent ejection of the ledger sheet before total printing when 40 the end of a sheet is reached at the same time that a group change occurs. Contacts are opened to prevent high speed ejection during printing operation. The tabulator is stopped while the platen is in a lifted, sheet receiving position.

45 Another object of the invention is to provide electrical control connections for automatically starting the record card controlled tabulator when the ledger sheet is in the proper posting position. The tabulator is also stopped automatically when the end of the sheet is reached.

50 A further object of the invention is to provide means for automatically ejecting the ledger sheet and lifting the platen when a change in record card group occurs during listing, said means being adapted also to carry out the same operations

after total printing when operating under tabulating control.

A feature of the invention is the provision of flash unit or group number indicating device for identifying a group of cards that are about to be tabulated. The operator is thus advised to select the proper account numbered ledger sheet which is due to receive a record of the items on the cards. A unique type of impulse controlled synchronous driving means is devised and placed between the tabulating mechanism and the indicating device. The indicator setting wheels are frictionally driven but normally latched and released for step by step movement under control of accurately timed impulses.

It is also an object of the present invention to provide a photocell controlled automatic ledger posting sheet feeding device. In this form, photoelectric sensing devices read the marginal perforations or marks on the ledger sheet and thereby control the fast feed, the line space and the printing position of the sheet.

A further object of the invention is the provision of a key controlled posting feed device. In this modification separate keys are provided for the high speed and line spacing controls so that an operator may enter a ledger sheet at high speed and then position it accurately with the slower line space feed. The marginal perforations act as a guide for the operator in the manual control of feeding. A single key is used for line spacing the platen and starting the tabulator.

Another object of the invention is the provision of progressive total printing and non-eject controls whereby a total may be printed at the top of a ledger sheet without causing the ejection of the sheet, which ejection happens later when a total is printed after the recording of items.

The foregoing and other objects of the invention will be apparent as the specification continues with reference to the drawings which form part of the specification.

Fig. 29 is a front sectional elevation view cut through the punching and sensing sections showing the arrangement of photocell sensing devices influenced by perforations in the margin of a ledger sheet.

Fig. 30 is a sectional elevation view taken along the line 30-30 of Fig. 29 showing the arrangement of mirrors to reflect rays of light through perforations in a record sheet so that the rays are thrown on the photocell elements.

Fig. 31 is a left elevation view of a modified form of platen control with keys which may be manipulated to control high speed feeding, line spacing and tabulator starting.

Fig. 32 is a plan view of the modified key controlled form of construction showing the top of the keyboard.

Fig. 33 is a sectional detail view through the punch frame showing how the end of a ledger

sheet is sensed by a contact which is provided when the modified key controlled form of mechanism is used.

Fig. 34 is a timing diagram of the machine divided into listing, tabulating, and total printing sections.

Figs. 35 and 35A when placed together form a wiring diagram of the electrical controls in and between the carriage and the tabulator. In this form of control, brushes sense the marginal perforations to regulate automatic insertion of ledger sheets.

Fig. 36 is a wiring diagram showing the arrangement used when photocells are employed to sense the position of the ledger sheet and control insertion thereof.

Figs. 37 and 37A together reveal a wiring diagram with the electrical controls arranged for manipulative key operation under control of the devices shown in Figs. 31 and 32.

The devices of the present invention in the disclosed embodiments are shown as attachments to the movable part of the paper carriage in a tabulating machine of kind revealed in the U. S. Patent 1,976,617. The machine is adapted to sense the data on perforated record cards and add and print a record thereof. The cards are arranged in groups according to a group number perforated therein and the machine may be set for listing to print a record of the data on each card of a group, or for tabulating to print only a record of the total amount of a group. The group number usually corresponds with or relates to some ledger number which identifies an account. The tabulating machine, through the group control devices, exercises control over the operation of the ledger posting sheet feeding devices. While operating in listing it is desirable to eject the ledger sheet when the end of a related group of records is reached. Then too, it is well to know which account is represented on the next group of cards to be sensed, so that the proper ledger sheet may be inserted in the machine. Both of these controls are exercised over the posting devices by the tabulating machine which initiates the ejection of a ledger sheet and sets up wheels to indicate the group number of the cards about to be sensed. When the tabulator is operating in tabulating, the ledger sheet ejecting means is operated after total printing on each group change.

The ledger posting devices in turn exercise control over the operation of the tabulator. The starting of the tabulator is automatically delayed until after the platen is lowered into the print receiving position and after high speed sheet feeding and line spacing have ceased. After a control break, the group control devices are reenergized under control of contacts closed as the platen is raised for the insertion of a ledger sheet. Other controls and interlocks between the tabulator and the ledger posting devices are described hereinafter.

The main purpose of the posting devices is to move a ledger sheet 50 (Fig. 20), to the correct printing position as rapidly as possible. If the ledger sheet already contains five lines of print, then when it is reinserted it is to be fed to the sixth line. A perforation 51 is punched in the right margin of the sheet for each line of print and it is through such perforations that electrical control of sheet feeding and positioning is established. The sample sheet shown is one that has been ejected twice. It first re-

ceived two items and then was ejected after the printing of an offset total. After being reinserted, three more items were printed in duplicate, and then the sheet was again ejected without receiving a total impression.

In Figs. 1 and 2 it is seen that most of the sheet feeding mechanism is at the left side of the platen 52. A platen driving motor M, a flash indicating unit F, and a housing H containing high speed, line space and platen lifting mechanisms, are all on the left side. At the right side of the platen is found a platen lifting handle 53, punching devices (Fig. 5) and perforation sensing brushes, Fig. 9.

The framework

A lower carriage frame 54 (Fig. 12) is fixed in the tabulating machine and a carriage slide 55 is movable thereon. Although for most printing operations the carriage is held in one position, all the ledger posting mechanism is mounted on side frames fixed to the carriage slide 55 so that the mechanism is movable sidewise with the platen into any tabular position. At the right side of slide 55, there is fixed to the slide a vertical side plate 56 (Figs. 2 and 3) and at the left side there is fastened a large castiron side frame 57 (Figs. 1, 2, and 12). Extending from the large frame 57 are three long bosses 58, 59 and 60 (Fig. 13) to which is attached a vertical bearing plate 61 (Fig. 11) under the housing H. A cover 62 (Figs. 1 and 2) encloses the mechanism on the side of frame 57 opposite to the housing cover H.

A rearwardly extending plate 63 (Figs. 2 and 3) is provided to form a fastening point for the right side of a paper table. The plate 63 is fastened at its front end by screws in an extension 64 on carriage slide 55. An angular offset arm 65 of plate 63 forms a brace which is also secured to the extension. Another extension plate 66 (Fig. 2) is fastened to cover 62 under the left edge of the paper table, in line with plate 63 at the right.

The platen suspending and lifting devices

The platen 52 is fixed to a shaft 67, Fig. 5, which is loosely pivoted in and suspended on a pair of arms 68 and 69 attached to a rectangular pivot bar 70. In Fig. 5 it is seen that the right end of platen shaft 67 is free to turn in a bushing 71 attached to arm 68, and said shaft extends to the right, out through a slot 72, Fig. 4, in plate 56, and ends in a manipulative knob 73, Fig. 2. The left end of the platen shaft is loosely pivoted in a bushing 74, Fig. 11, fastened to arm 69.

The left end of the pivot bar 70, Fig. 15, is formed as a trunnion 75 which pivots in a bearing 76 on the bearing plate 61. This end of the bar is also supported indirectly by the ball bearing 77 in frame 57. The right end of bar 70 is attached to a bracket 78 fastened to the arm 68 from which there extends a hollow journal 681 which is pivoted loosely on a bearing 79 fixed on the side frame 56. Thus, in effect, the bar pivots in the right side frame on the bearing 79.

When the pivot bar 70 is turned in a counter-clockwise direction, Fig. 16, the platen 52 is lifted from the lower print receiving position, Figs. 1, 2, 4, 5, 8, 11, 16 and 27, and swung through an arc of about 180° to the upper sheet receiving position, Figs. 3, 7, and 17. It is explained hereinafter how the bar 70 is automatically rocked

to lift and lower the platen. This may be done manually by operation of the lift handle 53 from the position in Fig. 4 to the position in Fig. 3 and back. The handle is attached to an offset extension 80 on arm 68 which is in turn attached to bar 70, so that an arcuate swing of handle 53 acts to swing and raise the platen just as does the rocking of bar 70. When in the lowered position, a shoulder on handle 53 rests on the top of frame 56. A hand rest bracket 81, Fig. 4, attached to frame plate 56 acts as a support or leverage point for the hand when raising handle 53 to lift the platen.

The paper guides

A large paper table 82, Figs. 2 and 3, is mounted a distance behind the platen and tilted slightly downward at the front end toward the platen. The sides 83 and 84 of the table are turned up to confine and guide the ledger sheets placed on the table. A pair of fastening brackets 85 extend down from the bottom of the table 82. The right bracket 85 (Fig. 3) is slotted to engage a stud 86 on plate 63 and provided with a stud 87 which may be fastened to a hub 88 on plate 63 by means of a screw 89, and the left bracket, Fig. 2, is attached to the plate 66 in a similar manner.

A small table 90 is arranged as a flexible forward extension of the large table 82 and it is secured thereto by a hinge 91. Upturned sides 92 and 93 of the small table are in alignment with the sides 83 and 84 of the large table. A pair of slotted links 94 pivotally attached to the sides 83 and 84 are loosely engaging the sides of the small table, permit it to rock up and down with the platen to a limited extent.

The platen frame carries a paper guide which is movable therewith so that it is at the correct angle for guiding the insertion of paper whether the platen is in the lowered or raised positions. A pair of arms 95 and 96 (Fig. 2) loosely pivoted on the platen shaft 67, carry the paper guide 97 which extends behind the entire width of the platen. The rear ends of the arms are pivoted at 98 to links 99 pivoted on studs 100 protruding from the frames. In Figs. 16 and 17 it is seen that the rear part of guide 97 is rounded for contact under table 90 when the platen is lifted. This part of the guide is bent in a U shape for strength and also to act as a support for the squared ends of arms 95 and 96.

A V shaped paper guide 101 extends across the carriage behind the platen and is fastened to the inside of arms 95 and 96. This guide separates the outgoing edge of the ledger sheet from the portion of the sheet entering the path around the platen.

When inserting the ledger sheet 50 for printing, it is placed upside down on table 82 (Fig. 2) with the top edge forward towards the platen. Then the right side of the sheet is brought into contact with the sides 84 and 93 and shifted forward under platen feed rollers and against paper stops. This places the perforated right margin of the sheet in a correct position with respect to the marginal sensing and punching devices.

The paper stops

A series of stops 103, Fig. 17, are brought against the platen to form a fixed limiting point for the forward edge of the sheet when it is inserted between feed rollers 102 and the platen when the platen is in the upper position. These

stops are retracted when the platen is lowered. From the end of each stop there branches out two U shaped arms which engage a shaft 104 pivotally mounted at the right end on a bracket 105, Fig. 5, attached to bar 70, and pivoted at the left end in an extension 106, Fig. 11, of arm 69. The arms of the stop permit it to slide vertically on shaft 104 toward and away from the platen. The movement of the stops is controlled by pins 107 (Fig. 5) extending from shaft 104 into slots 108 in the middle of the stops 103. A spring 109, coiled around a stud 110 on stop 103 and sprung behind a pair of studs 111 on bar 70, tends to urge the stop towards the platen so that two extending offset feet 112 are placed in contact therewith as seen in Fig. 17. The enlarged heads on studs 110 and 111 confine the springs 109 and hold stops 103 against the side of bar 70. When the platen is in the lowered position, the shaft 104 and the pins 107 thereon are held at such an angle (Fig. 16) that the stops 103 are lifted with the feet 112 away from the platen so that the record sheet may pass freely. The shaft 104 is held in that position by an operating arm 113, Fig. 11, secured thereto by screws 114. The end of arm 113 normally cooperates with the concentric edge of platen arm 95, Fig. 16, and thus holds the stops up, but when the platen and arm 95 is swung up, Fig. 17, the end of arm 113 drops into a notch 115 in the lower part of arm 95, rocking shaft 104 and pins 107 in counter-clockwise direction and permitting stops 103 to move against the platen. When the platen is lowered, the stops are quickly cammed out of contact by the cam action of the hook shaped edge of notch 115 on the end of operating arm 113.

The feed rollers

A number of feed rollers 102 are pressed into contact with the platen 52 and moved along therewith to wrap the ledger sheet 50 around the platen as it is lowered from the position shown in Fig. 17 to the position of Fig. 16. These rollers 102 are fixed on a shaft 116 (Fig. 2) which is geared to the platen by a pinion 117 in mesh with a gear 118 fastened to the platen. Shaft 116 is suspended near the platen by passing through hubs on a series of crank levers 119 pivoted at 120, Fig. 16, in a notch cut along the length of bar 70. A pointed tab extending from lever 119, fits in the notch and acts as a fulcrum about which the lever rocks. A curved leaf spring 121 is sprung between a notch in bar 70 and a depression in lever 119 and there acts to urge rollers 102 into contact with the platen.

A tail 122, extending from each of the crank levers 119, presses against the flattened side of a rod 123 which nests in a semi-circular groove along the side of bar 70. A paper tearing blade 124 secured to bar 70 is formed with a curved end wrapped around the outside of rod 123 to hold it on the bar.

Fastened to the rod 123 is an extension tab 125 which may be operated to turn the rod so that tails 122 are cammed from the flat part to the periphery of the rod. When this is done the front ends of the levers 119 are raised to carry the shaft 116 and the rollers 102 thereon away from the platen. As the platen and the associated parts are swung up (Fig. 17) near the end of the upswing a latch 126 engages the end of extension 125 to hold it as the other parts continue to move, with the result that rod 123 is rocked slightly in a clockwise direction and rollers 102

are separated from the platen so that a ledger sheet 50 may pass between them and end against stop feet 112. The rollers 102 are held in the separated position until the down swing movement of the platen is initiated, then, even before the platen starts to move, the latch 126 is tripped to release extension 125 permitting rod 123 to assume normal position under the pressure of tails 122 and springs 121, and freeing levers 119 to press rollers 102 against the sheet 50 to hold it on the platen as it is rocked and lowered. Latch 126 is formed as a ball, Fig. 11, pivoted on a stud 127 in frame 57 and provided with a stud 128 to which is articulated an operating link 129 which functions in a manner fully explained herein-after.

The ledger sheet punching and sensing devices

The devices for punching and sensing the marginal perforations 51, Fig. 20, in the ledger sheet 50, are located near the right end of the platen and held in a pair of insulation cylinders 130, 131, Fig. 7, attached to a flange 132 on a casting 133 formed with a long tube 134 projecting through arm 68 and side plate 56. Since the punch and sensing brushes are both mounted in the same framework, the frame is made shiftable so that either one may be brought into alignment with the marginal perforations of the sheet. The entire unit comprising cylinders 130, 131, and casting 133 is slideable along platen shaft 67 and movable in the bushing 79 on frame 56.

A pair of cam sleeves 135 and 136, Fig. 5, are used to cam the punch and brush unit frame over to the right, Figs. 7 and 8, so that the brushes are in effective position rather than the punch. The sleeve 136, Fig. 5, is slotted and a screw 137 tightens it to hold it fast to tube 134. Sleeve 135 is loose on tube 134 but confined laterally between side plate 56 and sleeve 136. This loose sleeve 135 is formed with two V notches 138 cooperating with two coinciding pointed cam points 139 on sleeve 136. A compression spring 140 projecting from a cylindrical hole 141, Fig. 9, in casting 133 is pressed between arm 68, Fig. 5, and casting 133 and thus tends to hold the points 139 of sleeve 136 in notches 138 or bearing against the side of the notches when the sleeves are moved relative to each other.

When the platen is lowered after a new ledger sheet is wrapped thereon, it is desired that the sensing brushes be in effective position to sense the perforations in the sheet and thereby control the feeding thereof to the correct printing position. The sensing unit is therefore cammed over to the right (Fig. 8) by means of a latch 142 which engages a notch 143 in sleeve 135 to hold sleeve 135 as sleeve 136 is rocked with the unit towards the end of lowering swing of the platen. With sleeve 135 held, and sleeve 136 still turning at that time, cam points 139 ride up the side of V notches 138 a distance sufficient to shift the unit so that the sensing brushes take the place of the punch. The pressure of points 139 against the side walls of the V notches 138 tends to turn sleeve 135, but the lower edge of notch 143 is engaged by the lug 144 on latch 142.

After the sheet is properly positioned and the sensing operation is finished, the tabulator is started and the sensing and punch unit frame 133 is released to move to the left so that the punch is in position to operate on the sheet along with the printing mechanism. The movement is initiated by tripping latch 142 so that sleeve 135 may turn to a position wherein points 139

are depressed fully into notches 138 and the sleeve 136 and the unit connected therewith are moved to the left by spring 140. Latch 142, Fig. 4, is pivoted on a stud 145 on side plate 56 and is formed with a bail offset 146 and an operating extension 147. A spring 148 coiled around stud 145, presses against latch 142 and urges it into cooperation with sleeve 135. Also mounted on stud 145 is a punch operating lever 149 formed with an offset ball 150. A stud 151 connecting the end of lever 149 to an operating link 152, is long enough to cooperate with extension 147 on latch 142. The other end of link 152 is articulated at 153 to a lever 154 pivoted on a stud 155 on frame 63. Also mounted on frame 63 are a pair of solenoids PS and SS with plungers 156 and 157 pivoted to lever 154 at 158 and 153. When the shift solenoid SS is energized, the plunger 157 is drawn to the right and the link 152 is drawn along therewith with stud 151 operating latch 142 in a counterclockwise direction to release sleeve 135 so that the unit may move to the left into the position shown in Fig. 5. This occurs early in the printing cycle so that later when the punch is operated it is in the correct position with respect to the margin of the ledger sheet.

The other solenoid PS, Fig. 4, attracts the plunger 156 and rocks the lever 154 in a clockwise direction to push the link 152. When so moved, the link turns the punch operating lever 149 in a clockwise direction to depress a tab 159 on the lever which extends through an opening 160 in frame 56. In Fig. 5 it is seen that tab 159 overlies one end of a punch lever 161 pivoted at 162 in a metallic insert 163, Fig. 10, held in cylinder 141 and secured to flange 132. The other end of lever 161 fits into a slot in the side of a punch 164 slideable in insert 163. A spring 165 pressing against lever 161, holds the punch normally retracted with a stop 166 on the lever against the side of flange 132 and the end of the lever contacting the under side of tab 159. A die plate 167 is secured to the underside of casting 133 with a die hole 168 aligned with punch 164. From the foregoing it is clear that every time solenoid PS, Fig. 4, is energized, link 152 is pushed, lever 161 is rocked clockwise, Fig. 5, and punch 164 is lifted, Fig. 10, to perforate a hole in the ledger sheet.

Link 152, Fig. 4, is restored in both directions by a pair of arms 169, 170 pivoted on a screw stud 171 fixed to frame 56. A spring 172 coiled around stud 171 and pressing against offset tabs on the arms, urges the arms together towards a centralized stop stud 173 on frame 56. Normally aligned with stud 173 is a pin 174 on link 152 also pinched between arms 169 and 170. Movement of link 152, backward for shifting the sensing unit, or forward for punch operation, results in a displacement of one of the arms 169, 170 with subsequent restoration thereby.

Turning again to consideration of the perforating operation it is noted that the chips, or circular paper punchings that are punched through die plate 167, (Fig. 10) are pushed into a circular opening 175 in casting 133. The front of the opening is plugged with an angular deflector 176 and the rear opens into a transverse opening in tube 134 with a plunger 177 at one end and a chip receiving box 178, Figs. 5 and 5A, at the other end. The plunger 177 is fixed in bar 70 so that motion of casting 133 causes the plunger to push the chips towards the box. The opening in tube 134 is slanted downward and

open at the bottom at the end coincident with an opening in a cylindrical bushing 180 secured to box 178. A ring clip 179 is snapped through slots in box bushing 180 into a circular groove near the end of tube 134 to hold the box on the tube. The box and bushing are free to turn on tube 134 so that they maintain an erect position as the punch and brush unit is swung up and down.

Whenever the platen is lifted, Fig. 7, the sleeve 135 is prevented from turning as far as sleeve 136, with the result that projections 139 ride up the sides of notches 138 to displace the sliding punch unit to the right. Sleeve 135 is stopped by an extension 181 thereon engaging the top of lug 144, Fig. 3. The reason that the punch unit is moved to the right when the platen is lifted is that it is necessary to see the procession of the marginal perforations past the punch position when the sheets are fed and positioned under manual control as explained hereinafter. The motion also serves to bring the brushes into alignment with the marginal perforations for controlling feeding automatically.

In Fig. 5 it is seen that the two insulation cylinders 130, 131 are of the same diameter as the platen 52. The ledger sheet bridges the space between the platen and the cylinders and overlies the punch 164.

A set of sensing brushes is provided to sense the marginal perforations 51 (Fig. 20) and thereby influence the feeding mechanism associated with the platen so that the ledger sheet 50 is fed to a posting position under the line of printing impressed on the ledger sheet the last time the sheet was in the tabulator. For example, if a sheet such as the sheet shown in Fig. 20 is threaded onto and around the platen and past the sensing brushes, the brushes sense the fact that the sheet contains five lines of printing and therefore should be spaced so that printing is started on the sixth line. There are three brushes pivoted in the space between the cylinders 130 and 131 (Fig. 5). The top brush 182 (Fig. 9) is used to control line spacing operation of the sheet. The second brush 183 is used to control high speed feeding of the sheet so that the sheet is forwarded rapidly from the entering position to within a few line spaces short of the correct printing position. The other brush 184 senses the passage of the end of a ledger sheet and controls the ejection of the sheet and lifting of the platen into position to receive a new sheet. The tips of the three brushes 182, 183 and 184 are spaced apart to engage the ledger sheet at intervals of four line spaces.

The line space control brush 182 is adapted to extend through perforations in the sheet and contact with roller 185 assembled over an insulation bushing 186 on an extension of the feed roller shaft 116. The roller 185 is held on the bushing by a shoulder thereon which in turn cooperates with a plate 188 secured to frame 133 in such position that the bushing and roller are held over brush 182. Attached to the top of bracket 78 is an insulation block 189 carrying a contact blade 190 bearing on the periphery of roller 185. In contact with blade 190 is another contact strip 191 (Fig. 5) which extends through a hole in arm 68 and bears against a fixed ring 192 embedded in an insulation collar 193 on hub 79. The mode of construction just described is used in order that an electrical connection may be made from a stationary contact member, such as ring 192, so that current may be conveyed to 75

a turning and shifting member, such as the contact roller 185.

The other two sensing brushes 183 and 184 are adapted to contact with an arc-shaped contact blade 194 (Fig. 9) fastened to an insulation bar 195 fixed to carriage frame 55.

The three sensing brushes 182, 183 and 184 are mounted in levers 196, 197, and 198 pivoted at 199, 200 and 201, respectively. The rear ends of 10 the levers are connected by a common link 202 attached to a spring 203 which draws the brushes out of sensing position when the platen is lifted. The tension of spring 203 is normally counteracted by a positive brush engaging arm 204 (Fig. 6) attached to pivot 201 which is in turn fixed to lever 198 (Fig. 9) and through 198 and link 202 positively connected to all brushes. When the platen approaches the lowered home position, arm 204 abuts against an extension 205 attached to an insulation bar 206 fixed on carriage frame 55. The cooperation of the parts is such that the arm 204 is rocked in a counterclockwise direction and the three brushes (Fig. 9) are rocked in the same direction to bear against the ledger sheet so that if perforations are encountered, the brushes reach through to touch the contact members.

Arm 204 is separated from extension 205 in the initial portion of the movement of the platen towards a raised position. As soon as arm 204 is released, spring 203 becomes effective to draw the sensing brushes out of effective position so that the brushes are held away from the ledger sheet during most of the time that the platen is traveling up to the raised position and held out throughout the time the platen remains in the raised position.

The extension 205 (Fig. 6) not only operates in a mechanical way to turn arm 204, but it also provides a path for an electrical current that continues through arm 204 and the various levers and link 202 leading to the three brushes.

The driving mechanism

At the left side of the machine is located a driving motor M (Fig. 1) which is geared to connections for line spacing the platen, high speed feeding the platen, lifting and lowering the platen, and operating the indicating wheels. The motor is attached to the main carriage frame 57 (Fig. 12) and its drive shaft 207 carries an operating pinion 208. In mesh with the pinion 208 is a gear 209 fastened to a pair of gears 210, 211 pivoted on a stud 212 on frame 57. A large gear 213 meshes with gear 211 and drives a line space operating shaft 214. Fastened to shaft 214 is a pinion 215 meshing with a large idler gear 216 pivoted on stud 217 and provided with a pinion 218 meshing with a gear 219 loosely mounted on the platen lifting drive shaft 220.

Another gear 221 is fastened to gear 213 for the purpose of driving the high speed platen operating mechanism. This gear meshes with an idler gear 222 pivoted at 223 and drives a gear 224 loosely pivoted on the trunnion 75 (Fig. 15) of the platen lifting bar 70.

Indicator setting wheels are driven by a train of gearing extending towards the rear of the machine. Gear 210 (Fig. 12) meshes with a gear 225 which in turn meshes with an other idler 226. In engagement with gear 226 is a gear 227 (Fig. 25) forming part of the friction clutch connections leading to the indicating setting wheels.

In addition to the indicator setting wheels adjusted through the friction clutch shown in Fig.

25, the indicator contains another set of numeral exhibiting wheels frictionally driven to positions corresponding to the setting of the first mentioned wheels. There is a direct connection from the platen lifting clutch shaft 220 to the operating shaft associated with the indicating wheels. This direct connection includes a sprocket wheel 228 (Fig. 12) attached to the end of platen lifting shaft 220 so that every time the platen is lifted, the group number of the next set of cards is indicated. Engaging the sprocket wheel is a chain 229 which is wrapped around another sprocket 230 fastened to an indicator operating shaft 231. Bearing against the rear side of chain 229 is a pressure roller 232 mounted on an arm 233 pivoted at 234 on frame 52. The roller tends to hold the chain taut and in full engagement with the teeth on the sprocket wheels 228 and 230.

The line spacing devices

The machine is provided with devices for spacing the ledger sheet line by line between operations of the printing mechanism. The line spacing operation is initiated by a magnet LM, Fig. 14, which, when energized, attracts an armature 235 fastened to a lever 236 pivoted on a stud 237. The end of lever 236 cooperates with a clutch pawl 238 pivoted at 239 on a disk 240 loosely mounted on the shaft 214. A spring 241 tends to turn the pawl 238 in a clockwise direction to engage it with the teeth on a clutch driving wheel 242 fastened to shaft 214, but the armature lever 236 is normally positioned to hold the pawl out of engagement. However, when magnet LM is energized, lever 236 is rocked in a clockwise direction and pawl 238 is released so that it also rocks in the same direction to engage the teeth on wheel 242 and form a positive connection between shaft 214 and disk 240. The connection is maintained for one revolution, after which the end of lever 236 again holds the pawl ineffective.

At the side of disk 240, Fig. 13, and fastened thereto, is a line space cam 243 which cooperates with a roller 244 on an arm 245 fastened to a shaft 246. Attached to the same shaft is another arm 247 tipped with an insulation finger 248 bearing against the top blade of a pair of contacts 249. Cam 243 is so shaped that shaft 246 is oscillated once each time the clutch is effective and the normally closed contacts 249 are opened near the midpoint of the cycle and again closed toward the end of the cycle.

Other contacts are closed by operation of magnet LM. Fitting into a hole in armature lever 236 is the end of a rod 317 the lower end of which is guided by an opening in boss 58 and bears down on an insulation piece over the middle blade of two pairs of contacts 318, 319. Contacts 318 are normally closed and contacts 319 are normally opened, but when magnet LM is energized, rod 317 is depressed to close contacts 319 and open contacts 318. The control exercised by these contacts is explained herein-after with reference to the wiring diagram in Fig. 35A. A set screw 320 limits the resetting movement of lever 236 as urged by the contact blade when magnet LM is deenergized.

To the outer end of the shaft 246, Fig. 12, is attached another arm 250 formed with a slot 251 which is enlarged at the ends and in the center. Fitting into one of the enlarged openings in slot 251 is a shoulder on a knurled knob 252, Fig. 11, slideable on a screw 254 fastened to a

line space pawl 253. The knob contains a compression spring which urges it towards the arm 250, but the knob may be grasped and pulled out of engagement with slot 251 and then adjusted to engage the shoulder of the knob with any of the three enlarged sections of the slot.

When pawl 253 is positioned on arm 250 as shown in Fig. 12, it is conditioned to impart three line spaces of movement to the platen. If the pawl is connected with the central enlarged opening in the arm 250, then, as the arm is depressed in operation, pawl 253 actuates the platen through two line spaces. When the pawl is connected to the slot opening near shaft 246, only one line space is caused by operation of the pawl.

The lower end of pawl 253 is confined by a bracket 255 on frame 51, and a spring 256 urges it into cooperation with a ratchet wheel 257, Fig. 15, which forms part of a platen driving tube 258 loosely pivoted on trunnion 75. The tube carries the inner race 259 of the ball bearing 77 in frame 51 and is formed with a driving gear 260, Fig. 11, meshes with a gear 261 on a hub 262 which is fastened to the platen shaft 67. Through the connections mentioned, counterclockwise operation of ratchet wheel 257, Fig. 12, is transmitted through gears 260 and 261 to turn shaft 67 and the platen in a clockwise feeding direction.

High speed feeding and ejecting devices

In order to save time in bringing a ledger sheet to the correct posting position, the machine is provided with means for turning the platen at a rapid rate. This high speed feeding means is controlled by the sensing brush 183 (Fig. 9) so that as long as the perforations 51 (Fig. 20) are sensed by the brush the rapid mode of feeding remains in effect. When the last or bottom marginal perforation passes brush 183, the high speed feeding devices are disconnected and the previously described line spacing devices are brought into effect under control of brush 182 which controls the energization of line space magnet LM for a few steps of line spacing motion to bring sheet 50 up to the proper printing position.

The high speed drive is conducted through a friction clutch composed of the gear 224 (Fig. 15) containing friction blocks 263 adapted to bear against a disk 264 attached to the driving tube 258. Gear 224 is wider than its driving gear 222 (Fig. 11) so that it may slide side to side and yet remain in mesh. As explained hereinbefore the platen driving tube 258 (Fig. 15) is loosely mounted on trunnion 75 and supported by ball bearing 77 and geared to the platen through gears 260 and 261 (Fig. 11).

The driving gear 224 (Fig. 15) is secured to a clutch operating collar 265 slidably mounted on the trunnion 75. The collar is formed with a groove 266 (Fig. 11) in which rides a roller 267 mounted on one end of an armature lever 268 pivoted at 269 on a bracket 270 attached to the side frame 51. Secured to the same bracket 270 is a high speed feed control magnet HSM in alignment with an armature block 271 fixed on the lower end of lever 268. A compression spring 272 (Fig. 15) coiled around the stud 273 fixed to bracket 270, bears against the lower end of lever 268 and tends to rock it in a counterclockwise direction (Fig. 11) to position the collar 265 towards the left to disconnect the clutch elements 263, 264 (Fig. 15). A screw 274 is adjustable to

limit the extent of movement of lever 268 in a direction to disconnect the clutch.

When magnet HSM is energized, through the sensing brush 183 analyzing perforations in the ledger sheet, it attracts the armature block 271 and rocks lever 268 (Fig. 11) in a clockwise direction to force collar 265 to the right and press friction blocks 263 against the side of disk 264. Thus the gearing connections to the motor M through gear 226 are frictionally connected to the platen driving tube 258 which continues in high speed operation as long as magnet HSM is energized. As soon as the end of the column of marginal perforations 51 is sensed on the ledger sheet the magnet HSM is deenergized and spring 272 acts to disconnect the high speed clutch.

Whenever the high speed connections to the platen are in operation a detent cooperating with a star wheel 330 (Figs. 1 and 11) for line spacing, is disengaged so that the attendant clicking noise is eliminated, and the drive is unobstructed. Wheel 330 is fastened to the bushing 262 which is clamped to the platen shaft 67. Cooperating with the teeth on the star wheel is a roller 331, Fig. 12, on a detent arm 332 pivoted on a stud 333 fixed on the platen swinging frame 69, Fig. 11. The arm carries another roller 334 (Fig. 12) which is engaged by the end of an operating lever 335 pivoted at 336 on casting frame 57. Connected to lever 335 at 337 is one end of a link 338 the other end of which is pivoted on a plunger 339 in a detent release solenoid DRS fastened to a bracket 340 riveted to frame 57. Every time that the solenoid is energized, plunger 339 and link 338 are moved to the right, lever 335 is rocked in a clockwise direction and engages roller 334 to rock detent arm 332 in a counterclockwise direction to remove roller 331 from between the teeth of the star wheel. A spring 341 tends to keep the detent engaged with the star wheel.

The high speed driving connections are not only used to insert a sheet under control of brush 183, but they are also used to eject the sheet independent of brush control. For ejection, the magnet HSM is energized by the tabulator group control devices whenever card group numbers change. The control over ejection is described more fully hereinafter with reference to the wiring diagram.

The platen raising and lowering devices

It is explained hereinbefore how the platen may be raised for the insertion of a sheet and lowered in position for printing by operation of a handle 53 (Figs. 3 and 4) on an extension 88 formed as part of arm 68 (Fig. 5) connecting the platen shaft 67 to the swinging bar 70. In addition to this manual means for operating the platen, the machine is provided with a lever controlled automatic means for swinging the platen up and down under control of the platen control lever 275 (Figs. 1, 2, 13, and 14) projecting above a slotted table 276 fastened to the top of housing H and frame 57. The machine also contains electric controls for automatically operating the platen raising devices when the end of a ledger sheet is sensed. After the platen is so raised and a new sheet is inserted, operation of the tabulator and the sheet feeding devices is initiated by manipulation of lever 275 to lower the platen and automatically start feeding the ledger sheet under control of the perforations thereon and initiate record card feeding under control of the ledger sheet when it is in the correct printing position.

As explained hereinbefore, the platen may be

raised and lowered by rocking bar 70 (Fig. 15) through an angle of about 180°. The left end of this bar is rocked on the trunnion 75 supported in bearing 76. Near the bearing is a gear 277 clamped to trunnion 75 and adapted to rock bar 70 when it is oscillated by a segment 278 (Figs. 13 and 14) loosely pivoted on a shaft 279. The sector is driven through a clutch mechanism on shaft 220 operated under control of a clutch releasing magnet PRM.

Fixed to the normally idle shaft 220 (Fig. 14) is a cam 280 carrying a clutch pawl 281 (Fig. 13) pivoted at 282. A spring tends to engage the pawl with a constantly rotating notched wheel 283 fastened to the drive gear 219, but the pawl is prevented from moving in a counterclockwise direction by the end of an armature lever 284 pivoted on a stud 285 projecting from the side frame. A spring 286 attached to the armature lever 284 holds it against a stop pin 287a fixed to place the end of the armature lever in position to obstruct the end of pawl 281. However, when the platen raising magnet PRM is energized, the armature lever 284 is rocked in a counterclockwise direction and the clutch pawl is released to connect the rotary wheel 283 to the cam 280 and drive shaft 220.

At the side of cam 280 (Fig. 14) and attached thereto is a notched operating collar 287 cooperating with a rearwardly extending arm on the sector 278. This arm of the sector is shaped with a projection 288 extending in a path of a shoulder 289 cut in the periphery of collar 287. When the clutch connection is made, collar 287 is driven positively in a clockwise direction (Fig. 14) and cooperates with the extension 288 to rock the sector 278 in a counterclockwise direction about shaft 279. This is done to start the operation of the gear 277 (Fig. 11) to rock the bar 70 and start the swing of the platen towards a raised position. After the initial inertia is overcome by this positive method of actuation, the further operation of the sector 278 is carried on by cooperation of the cam 280 (Fig. 14) with a roller 288 pivoted on the side of the rearwardly extending arm of the sector.

The sector carries a stud 289' cooperating with an insulation piece on the center blade 290 of a pair of contacts 291, 292. When the sector is in its normal position the stud 289' holds the blade 290 raised so that contacts 291 are closed and the contacts 292 are open. However, as the sector is operated, stud 289' is lowered and contact blade 290 follows along therewith to close contacts 292 and open contacts 291. The posting interlock control exercised by these contacts is explained hereinafter with reference to the wiring diagram.

After the cam plate 280 passes through a half revolution, the end of pawl 281 mounted thereon strikes against the top of a disengaging lever 293 (Fig. 13) pivoted on the stud 294 in the side frame. Thus, the clutch is disconnected to hold the cam 280 in a position wherein the high point of the cam cooperates with the roller 288 to hold the sector 278 in a fully operated position wherein the parts are moved to such an extent that the platen is lifted to its extreme upward position. The platen is held in this raised position until the lever 275 is operated. A spring 305 urges lever 293 in a clockwise direction against a stop stud 310 for holding it in normal position.

The platen lowering control lever 275 is pivoted on a rod 295 and held in normal position

against a stop rod 296 by a spring 297. The lower end of the lever carries a flipper 298 pivoted at 299 and held in position with a tab 300 thereon against the side of the lever as urged by a spring 301 attached to the lever. When 5 the upper end of lever 275 is depressed, the lower end (Fig. 13) is moved to the right and a cam face on flipper 298 cooperates with a lug 302 formed on a bell crank 303 pivoted on rod 304. The lower vertical arm of bell crank 303 cooperates with the side of lever 293 to rock it in a 10 counterclockwise direction to release pawl 281 and connect the clutch for continuance of its operation through the remaining 180°. The horizontal arm of bell crank 303 and lug 302 overlies an extension on the armature of lever 284 so that operation of lever 275 serves to move both 15 of the clutch pawl retaining means with the effect that if the platen is raised when the lever is operated, the platen will be lowered and if 20 the platen is in its lower printing position, it will be raised when the lever is operated.

When the platen operating clutch is in the middle of its operating cycle, a shoulder 306 on collar 287 (Fig. 14) cooperates with the side of 25 the vertical arm of a bell crank 307 pivoted on a stud 308 extending from bearing plate 61. The forwardly extending arm of bell crank 307 underlies the roller 288 on sector 278 and the connections made through bell crank 307 are in 30 preparation for the restoring movement of the sector. A pin 309 (Fig. 13) limits the extent 35 of movement of the bell crank 307 in a counterclockwise direction. When lever 293 is operated to again engage the clutch for continuance of the platen operating cycle to lower the platen, collar 287 (Fig. 14) through shoulder 306 actuates bell crank 307 in a counterclockwise direction causing it to push upwardly against stud 289 and start motion of the sector 278 in a clockwise direction. When once started toward its lowered position, the weight of the platen and its connections tends to carry the platen down at an accelerated speed, but the rate of fall is controlled by the contour of cam 280.

A detenting device is provided to locate the gear 277 (Fig. 14) in the two positions to which it is turned by the sector 278. Attached to gear 277 is a detent plate 311 notched out at 312 so that a roller 313 on an arm 314 loosely pivoted on shaft 279 may engage therein to locate the gear after it has been turned through an angle of about 180°. A spring 315 attached to arm 314 forces it against the periphery of detent plate 311 and acts to force the gear 277 to, and hold it in, the proper position. As the gear 277 and the connected detent plate 311 are turned back in a counterclockwise direction by the restoration of the sector 278, a rising cam surface on the detent plate cooperates with the roller 313 and tends to slacken the momentum of the falling platen. After the platen reaches the lowered position, it is impositively held therein by roller 313 resting on a slanted edge of detent plate 311.

A rebound preventing latch 342 (Fig. 13) is provided to drop in behind either of two projections on a latch plate 343 (Fig. 14) secured to cam 280. The latch 342 is pivoted on a stud 344 fixed in bearing plate 61 and is drawn down into latching position by a spring 345. Just before the instant that cam plate 280 is suddenly stopped by either lever 284 or arm 293, latch 342 drops off one of the two high points on plate 343 and 70 into abutting position before a shoulder thereon, 75

so that reversal or rebounding of the clutch operating parts is prevented in either of the stopping positions.

When the platen is in the raised position with the pressure rollers separated therefrom and the platen operating lever 275 (Fig. 13) is operated, connections are moved to release the holding means cooperating with the pressure rollers 102 (Fig. 17) so that they clamp the paper against the platen before the platen is lowered. A link 129 (Fig. 13) is slotted at its upper end and encircles a pin 318 on the side of lever 275. The lower end of the link 129 carries the stud 128 which connects the link to the front end of the pressure roller latch 126 (Fig. 17). When lever 275 is operated, the link 129 is raised before flipper 298 cooperates with the lug 302 on bell crank 303. This is done in order that link 129 may release the pressure rollers 102 so that they may hold the ledger sheet 50 on the platen before the platen is lowered.

The head spacing devices

In order that the first posted item may be spaced below any heading data printed at the 25 top of the ledger sheet 50, devices are provided to turn the platen and feed the sheet as it descends from the raised position to the printing and punching position. The number of line spaces that the sheet is to be fed in this manner is predetermined by manipulation of a knob 350 (Fig. 1) attached to a graduated disk 351 (Fig. 11) extending through a hole in the housing H. The disk may be adjusted with respect to a mark 30 at the edge of the hole in the housing and thus 35 select the placement of the first perforation 51 (Fig. 20) and the first line of print. As shown in Fig. 20 the sheet 50 is printed and punched as if spaced for one heading space; the first line of 40 item print appearing about six lines below the first or top marginal control perforation 51.

The disk 351 (Fig. 11) is fixed to a shaft 352 which slides and turns in bushing 353 and boss 354 extending from plate 61 and frame 57, respectively. Attached to shaft 352 is a head spacing control cam 355 and a positioning arm 356 clamped to the shaft by screw 357. The positioning arm carries a stud 358 adapted to enter one of a series of holes 359 (Fig. 13A) perforated 50 near the rim of a complementary head spacing control cam 360. A compression spring 361 (Fig. 11) presses between bushing 353 and side of disk 351 and thus tends to hold shaft 352 to the left with stud 358 held in engagement with one of the holes 359 in cam 360. However, the operator 55 of the machine may grasp knob 350 and push the shaft inward to release positioning arm 356 from cam 360 and turn the shaft to the desired degree of adjustment and then permit the shaft to move outward when stud 358 coincides with the selected hole 359. In this way the initial movement 60 of the ledger sheet to bring the first line of print a desired number of spaces below the heading may be selected by an adjustment according to the graduations marked on the exterior of the disk 351 (Fig. 1).

Cam 360 (Fig. 11) is attached to a gear 362 and a sleeve 363 loosely mounted on shaft 352. The sleeve is grooved at 364 and into the groove 70 is fitted an extension of a block 365 fixed on the plate 61 by screw 366. The connection between block 365 and sleeve 363 holds cam 360 and gear 362 in position on shaft 352 and prevents these parts from following positioning arm 356 when 75 it is shoved to the right during adjustment.

The head spacing adjusting devices already described provide a means for varying the relationship between the cams 355 and 360 connected to gear 362 through arm 356 and shaft 352. When once set, the cams turn in unison, driven by gear 362 which is in mesh with the platen raising and lowering gear 277. It is described hereinbefore that gear 277 is rocked back and forth by sector 278 in order to lift and lower the platen. Accordingly, when the platen is thus operated, cams 355 and 360 are moved back and forth so that the cam faces thereon are active to control the latching of the platen drive gearing.

Extending from frame 57 (Fig. 11) is a stud 367 carrying a U-shaped latching member 368 loosely pivoted thereon. A coil spring 369 on the stud tends to turn the latching member 368 in a clockwise direction (Fig. 18) so that lugs 370 and 371 on the member are pressed against the periphery of cams 360 and 355, respectively. The right arm of member 368 (Fig. 11) which carries lug 371 also carries another latching extension 372 (Fig. 18) which is adapted to cooperate with ratchet teeth 373 cut in the periphery of the high speed clutch disk 264 (Fig. 15). This disk 264 normally rotates idly when the platen is raised and lowered. In Fig. 19 it is seen that when the platen is raised and platen shaft 67 swings about trunnions 75 in an upward direction, gear 261 operates gear 260 and the connected disk 264 in a counterclockwise direction. When the platen is again lowered, shaft 67 swings in a clockwise direction about trunnion 75 and gear 261 tends to turn the disk 264 in a clockwise direction. If the disk is not obstructed in its motion during the platen raising and lowering operations, the ledger sheet will remain in a fixed position with relation to the platen throughout the operation lowering the platen. However, if disk 264 is obstructed from motion in a clockwise direction during the lowering of the platen, then the attached gear 260 (Fig. 18) also remains stationary and acts as a planetary driving gear to turn the swinging gear 261 and the attached platen in a clockwise direction so that the ledger sheet thereon feeds with relationship to the platen. The amount that the sheet is fed depends on the time that the disk 264 is latched during the platen lowering operation and this in turn is controlled by the time that the latching member 368 is allowed to rock in a clockwise direction to place latching projection 372 in engagement with the teeth 373 as determined by the contour of cams 355 and 360.

A concentric portion of the periphery of cam 360 normally underlies lug 370 (Fig. 18) and positions member 368 so that latch projection 372 is held out of engagement with teeth 373. The same concentric edge of cam 360 is effective when the platen is in the raised position (Fig. 19) and for a short interval of time during the lowering of the platen. However, as the platen is lowered the cam 360 is turned and there comes into cooperation with lug 370 a depression 374 in cam 360 permitting member 368 to rock in a clockwise direction if permitted to do so by the other cam 355.

Since both cams 355 and 360 are connected to gear 362 they are rocked approximately 180°, first in a clockwise direction (Fig. 18) and then 70 in a counterclockwise direction due to the action of sector 278 when the platen is raised and lowered. As the cams are so moved, a projection 375 on cam 355 cooperates with lug 371 and determines the time at which latching member 368 75

is to be rocked to disengage latching extension 372 from teeth 373. The placement of this rise 375 on cam 355 is in turn dependent upon the predetermined adjustment of the head spacing devices. Cam 355 is formed with a concentric periphery marking the end of rise 375 which may be placed under lug 371 so that member 368 is prevented from rocking into a latching position throughout the platen lowering stroke. Thus, 10 when the depression 374 underlies lug 370 to permit latching by member 368, cam 355 may be positioned to hold up lug 371 to prevent such latching operation and thereby prevent any amount of head spacing. The greater the distance between the depressions 374, 375 of the cams the longer will be the period in which extension 372 will engage teeth 373 and greater will be the planetary action of the gearing to turn the platen for head spacing operation as it is lowered.

The indicating mechanism

The machine is provided with an indicator F (Fig. 1) to indicate the group number of the perforated record cards which are about to be analyzed by the tabulator. This group number corresponds to the ledger account number identifying the ledger sheet which the operator is supposed to insert in the machine before the related group of cards controls printing. The number is flashed when the platen is raised after the ejection of a ledger sheet, thereby conditioning the machine for the reception of a new ledger sheet and at the same time informing the operator regarding which sheet is to be selected for operation.

The tabulator is provided with a double set of sensing brushes. The upper brushes are used merely to control operations while the lower brushes control accumulation and printing in the usual way. Because of this form of construction, it is possible to operate such an indicator F under control of the upper brushes before the related group of record cards are analyzed for printing control under the lower brushes. The record cards are encountered first by the upper brushes and then by the lower brushes so that a group number may be read off the first card of an incoming group at the same time that printing is controlled by the last card of an outgoing group.

The indicating mechanism is mounted on a base 380 and located between a pair of side frames 381, 382 fixed to the base. Shafts 383, 384 and bar 385 act as bracing members between the side frames. A cover 386 conceals the mechanism, but is formed with a sight opening 387 through which the numerals on the indicator wheels may be observed. The right frame 382 is secured to the main casting frame 57 so that the indicator unit extends to the left as viewed in Fig. 1.

The indicator unit comprises two sets of indicator wheels and two forms of driving mechanism. The one set of wheels is used to set up a number controlled by impulses emitted by the tabulator and directed through a magnetically controlled clutch. The other set of wheels is used to indicate the setting of the first mentioned set of wheels and it is driven by gearing connected to the platen raising mechanism. The indicator setting wheels and driving means therefor will be considered first.

It is noted hereinbefore in the description of the driving mechanism that the gear 227 (Figs. 12 and 25) is driven continuously as long as the

motor M is energized. This gear forms part of a housing 388 containing the indicator clutch magnet ICM. Secured to the periphery of this housing 388 is a pair of conducting rings 389 separated by insulation rings 390. The housing is loosely pivoted on a stud 403 extending from the side frame 57. Wiping on the rings 389 as they are turned by gear 227 is a pair of brushes 391 which convey current to the rings so that wires may be led from the rings to magnet ICM. The brushes are mounted on an insulation block 392 fixed to the side of frame 57.

The magnet ICM forms part of a magnetic friction clutch comprising a plate 393 covered with fibrous material 394 which may be pressed against the side of housing 388 when the plate is attracted by the magnet. The energization of the magnet is timed to coincide with the time of operation of the tabulator during which the ten digit index points are analyzed on the record card.

Attached to clutch plate 393 (Fig. 25) is a Geneva pin driving wheel 395 (Fig. 21) loosely mounted on a sleeve extension of housing 388. This wheel carries four pins 396 which are adapted to engage in slots 397 of a Geneva wheel 398 loosely pivoted on a stud 399 extending from frame 57. The pin wheel 395 also carries a set of four projections 400 adapted to cooperate with an armature latching lever 401 (Fig. 12) pivoted on a stud 402 on frame 57. Cooperating with latch 401 is an indicator release magnet IRM which when energized swings the latch counter-clockwise out of the path of a projection 400 so that the magnetic clutch wheel 398 may be turned one step. This magnet is energized at regular intervals under control of circuit breaker contacts operated by the tabulator. Although the friction clutch tends to turn the pin wheel 395 through a greater arc than the quadrant between projections 400, the impulses control latch 401 so that the pin wheel is regulated in synchronism with passage of the record card in the tabulator so that each step of motion of the pin wheel coincides with the travel of the card between two successive index points in a column of the record card. Thus, the indicator mechanism is synchronized with the tabulator mechanism without any direct mechanical connections. Latch 401 vibrates back and forth ten times during the analysis of each record card.

The driving connections from the friction clutch continue from the Geneva wheel 398 (Fig. 21) through a gear 404 attached thereto and in mesh with an idler gear 405 loosely pivoted on a stud 441 on frame 57. This gear 405 in turn meshes with a gear 406 attached to a shaft 407 leading into the indicator unit (Fig. 24).

Attached to shaft 407 are a series of ten indicator drive pinions 408 (Figs. 24 and 26) one for each indicator wheel. Each pinion meshes with teeth 409 on an outer shell 410 of an indicator setting wheel made with an inner shell 411 welded to the outer shell. Shell 410 is fastened to a hub 412 loosely mounted over a bushing 413 on the indicator operating shaft 231. This shaft and the bushings 413 thereon do not play any part in the adjustment of the setting wheels; they are used merely as pivot stations for the loose hubs 412 of the wheels.

A flange 415 on inner shell 411 contains a series of eleven holes aligned with a similar series of equally spaced holes arranged in a circle near the edge of the outer shell 410. In each aligned pair of holes in the shells there slides a setting

pin 416 with an enlarged head 417. There is a shoulder on the end of the pin opposite to head 417 to prevent the pin from slipping out of the shells. Fastened to the flange of inner shell 411 is a thin strip 418 of spring steel with offset tails pressing against the sides of pins 416 to hold the pins frictionally in or out of adjusted position. The normal position of the pins 416 is the one shown in Fig. 26 where it is seen that the head 417 is fully extended and the inner end of the pin 416 is out of the path of a stop lever 419 (Fig. 24) mounted on a numeral indicating drum 420.

The setting wheel with the pins 416 is turned in synchronism with the passage of the record card past the upper brushes of the tabulator by the gear connections (Figs. 21 and 24) to the magnetic clutch (Fig. 25) which is timed by release magnet IRM (Fig. 12) as already explained. Thus, the pins 416 are moved in succession past an operating bail 421 (Fig. 24) pivoted at 422 on the sides of bar 385. The bail is adapted to be swung on the bar so that a forward extension 423 presses against the head 417 of pin 416 and moves it in the shells so that the inner end is in the path of stop 419. The bail is formed with a depending slotted end 424 into which is inserted the end of an armature lever 425 operated by an indicator control magnet IM.

Fastened to base 380 (Figs. 22 and 24) is a series of brackets 426 each with a pair of rearwardly extending rectangular extensions 427 and 428 which form cores for a pair of wire coils comprising the indicator control magnet IM. There is provided one such control magnet for each numeral exhibiting indicator drum 420. Magnet IM is energized under control of an upper brush in the tabulator when a perforation such as those representing the group number 746 (Fig. 28) on the card is brought under the brush.

The armature lever 425 (Fig. 24) is pivoted on a pair of studs 429 extending from the lower core 428. A leaf spring 430, attached to the upper core 427 by screw 431, is curved to contact the lower end of lever 425 (Fig. 22) and urge the lever in a counterclockwise direction to hold bail 421 in an ineffective position. When magnet IM is energized, lever 425 is attracted in a clockwise direction into contact with the upper core 427, and bail 421 is rocked in a counterclockwise direction to press end 423 (Fig. 24) against the head of whichever pin 416 happens to be passing at the time, and thus shoves the pin into the path of stop 419. As lever 425 moves into contact with core 427, an upper end 432 of spring 430 presses against the lever to aid the lower end of the spring in restoring the lever as soon as magnet IM is deenergized.

The pins 416 do not have any fixed numerical relationship with respect to the stop lever 419. The indicating value of the operated pin depends on the time that it is operated, and that in turn depends on the location of the group number perforation in the record card. For example, if the group number is 9, the corresponding perforation is analyzed early in the cycle, magnet IM is energized early in the cycle, a pin is depressed early in the cycle and it then travels through almost a complete circle before being brought to rest after ten steps of movement of the setting wheel. When a zero perforation is analyzed, the operated pin 416 travels only one step away from bail 421 before shell 410 is brought to rest by the completion of the circuit breaker impulse actuation of magnet I RM. A

diagrammatic showing of the sensing of a 5 perforation and the consequent operation of magnet IM and pin setting bail 421 is presented in the last three lines of Fig. 34. When one positioned and stopped, the pins 416 are locked in position by the gearing (Fig. 21) to the Geneva drive wheel 395.

The pins 416 are set up on every listing and tabulating cycle of the machine but the setting is only used for actual indication after a change in group number, at which time a ledger sheet is ejected and the platen is raised for the insertion of another ledger sheet.

When the platen is raised, the raising clutch shaft 220 (Fig. 12) is turned 180° in a counter-clockwise direction and the sprocket 226 thereon is turned a half revolution. The other sprocket 230 connected to sprocket 228 by chain 229 is turned a complete revolution in the same direction. Shaft 231 connected to sprocket 230 is also turned one revolution in the same direction.

Mounted on shaft 231 (Fig. 26) are the bushings 413 with shoulders for the loosely mounted indicator drums 420. Between each pair of bushings there is keyed to the shaft friction washer 433 which presses against the inner wall of drum 420 and tends to turn the drum with shaft 231. The drum turns clockwise (Fig. 24) until the stop lever 419 thereon strikes a depressed pin 416 which locates it in the proper numeral indicating position.

The platen raising and drum turning operation always occurs at the end of a cycle at which time the pin setting wheels of the indicator are at rest.

Stop lever 419 is pivoted on a stud 434 protruding on the inside of drum 420. A spring 435 wound on stud 434 is caught under a lug 436 bent in out of the side wall of the drum. The other end of the spring presses under a bail formation 437 on lever 419 to rock the lever in a counter-clockwise direction so that normally a tail thereon rests on the outer edge of the lug 436. The spring forms a yielding control for lever 419 so that if a depressed pin moves to pass it in a clockwise direction (during setting operation) the lever yields by rocking on stud 434 in the same direction. The same spring holds the lever in a position wherein an offset tab 438 thereon is in line with the circle of pins 416 and in the path of a depressed pin so that when the drum 420 is turned in a clockwise direction it moves until tab 438 abuts against the pin.

The construction and mode of operation described with respect to one drum and one set of indicating elements is the same for all ten indicators. In the higher orders of the indicator where no perforations are sensed in the card, a zero impulse is automatically initiated at the proper time to push in the pins 416 so that the drums of the related orders indicate zero.

The indicator drums 420 remain in the adjusted indicating position between platen raising operations. When the drums are operated they turn directly from an old setting to a new setting, always moving in the same direction, without having or going back to any home position.

As the platen swinging devices are operated to lower the platen, shaft 231 is again operated to turn clockwise (Fig. 24) one complete revolution, but the indicator drums remain in the adjusted positions because they are stopped positively by the extended pins 416, and the drive is only fric-

tional through the contact of spring washers 433 (Fig. 26).

The pin setting wheels also turn in the same direction at all times, with the depressed pin 5 416 being restored as it approaches the operating bail 421. For a restoring means the indicator is provided with a series of wires 439 (Fig. 26) clamped to the top of bar 385 by screws 440. There is a wire for each set of pins 416. The 10 wire 439 is bent down (Fig. 24) and curved into the path of the pin head 417 so that the pin is cammed out to normal position as it passes near the top of bar 385.

The printing devices

15 The devices for printing on the ledger sheet are controlled by the record card sensing means in the tabulator. A printer control magnet PM (Fig. 27) is energized at a differential time according to the time of sensing a perforation in the record card 49 by a lower brush. Moving in synchronism with the feeding of the card is a typebar 445 formed with notches 446 that moves in succession past a stop pawl 447. When magnet PM is energized it attracts an armature lever 448 to which is attached a call wire 449 connected at the opposite end to a latch 452 for releasing pawl 447. Thus the typebar 445 is stopped differentially by the pawl engaging in one of the 20 notches 446; the bar stopping between hammer 450 and platen 52 to place at the printing line, a type 451 corresponding to the perforation sensed. There is provided for each order or denomination, a set of printing elements such as 25 those described. For a more detailed study of the printer, reference may be made to Patent No. 1,976,617.

The electrical control devices

30 Reference may be made to Figs. 35 and 35A for an understanding of the electrical wiring in and between the tabulator and the posting carriage for automatic insertion of a ledger sheet under sensing brush control. The wiring shown in Fig. 35 is of the standard tabulator form such as disclosed in Patent No. 1,976,617 with the exception of contacts 460 and 461. The upper part of Fig. 35A shows the sensing and group control wiring of the tabulator while the lower end of the diagram shows the electrical controls on the carriage for controlling it and the tabulator.

35 As the perforated record cards 49 (Fig. 28) move through the machine in succession, they first pass under upper brushes UB (Fig. 35A) and then one cycle later they pass under lower brushes LB. The upper brushes UB form part of the group control devices for comparing successive cards and, in the present case, they also control the indicating mechanism to reveal the 40 group numbers on the cards. The lower brushes LB in addition to forming part of the group control devices, also control the adding and printing mechanisms.

45 A switch S (Fig. 35) is closed to connect the main lines 464 and 465 to the source of current.

50 The presence of cards at the upper and lower card sensing stations is manifested by the closure of card lever contacts 462 and 463 (Fig. 35) operated by the cards as they pass the stations. Closure of contacts 462 completes a circuit from line 464 through wires 466, 467, magnets UCL and UCL₁, contacts 462 and line 465. Magnet UCL₁ closes contacts UCL₁ to provide a shunt holding circuit around contacts 462 through contacts 70 UCL₁, contacts L5 and wire 468. As long as 75

record cards continue to pass the upper brushes, magnet UCL will remain continuously energized since contacts L5 are timed to be closed during the interval that the card levers open. The lower card lever contacts 463 similarly complete a circuit from line 464, wire 468, magnets LCL and LCL1, wire 468', contacts 463 and line 465. The closure of contacts LCLb sets up a holding circuit through cam contacts L6 the timing of which is the same as that of contacts L5. The energized card lever magnets UCL and LCL control many of the circuits throughout the machine as described hereinafter.

After the record cards are placed in the tabulator the machine is ready to start card feeding and sensing operations. Depression of a start key to close contacts ST will complete a circuit as follows: from line 464 (Fig. 35), closed contacts P1, the tabulating clutch magnet TCM, contacts 27, start relay STR, start key contacts ST, stop key contacts SP, special end of paper controlled contacts, 460, group controlled relay contacts 469, to line 465. Energization of magnet TCM causes opening of contacts 27 and the circuit is then changed to include the operating relay magnet OR which is wired in parallel with the contacts 27. Magnet OR then closes its contacts 470 to complete a circuit through the tabulating motor TM as follows: from line 464, motor TM, contacts 470, to line 465, thus initiating operation of the tabulator.

The tabulator is provided with an automatic restart switch ARS which, when closed, directs current through the start relay STR after a resetting and total printing cycle without need for depression of the start key. At the end of a total printing operation, contacts P2 close to make the shunt around the start key effective through the switch ARS, contacts P2 and contacts LCLa closed by the lower card lever relay LCL. The present invention provides means for automatically restarting the tabulator when a newly inserted ledger sheet is properly positioned for posting. Switch ARS is opened for this control. The posting restart control includes a wire 471, contacts 461 and wire 472 connected in shunt around the start key and auto start contacts. The contacts 461 are closed at the proper time by a carriage controlled relay SR as explained hereinafter.

Automatic group control devices are provided to compare the group number sensed on one card under the lower brushes with the group number on the following card under the upper brushes. When the group numbers disagree, card feeding is stopped, total taking and resetting takes place, and the posted ledger sheet is ejected. The control devices are of the single polarity, balanced relay type such as the control means disclosed in the Bryce Patent No. 1,902,013 and the Smith Patent 1,933,349. A number of double coil relays are provided with a coil GCA (Fig. 35A) for each upper control brush UB and a coil GCB for the related lower control brush LB. These coils cooperate with a balanced armature construction which serves to hold control contacts GC closed if both coils are energized at the same time or if neither are energized, but effects opening of the contacts if one coil is energized while the other is deenergized. Since the index point positions on the card passing the lower brushes are analyzed concurrently with the analysis of the corresponding index point positions of the following card passing the upper brushes, perforations occurring in any

index point position of both cards will complete a circuit at a time in the cycle of the machine corresponding to the location of the perforation. The circuit is as follows: from line 465, circuit breaker contacts CBC, upper card lever contacts 473, contact roller 474, a perforation in the card, upper brush UB, a plug wire 475 to indicator socket 476, plug wire 477, coil GCA, wire 478, contacts L12 closed during analysis, and wire 479 to line 464. Arranged in parallel therewith, and energized at the same time when group numbers agree, is the circuit through coil GCB: from line 465, contacts CBC, lower card lever contacts 480, contact roller 481, a perforation in the card, lower brush LB, plug wire 482, coil GCB, wire 478, contacts L12 and wire 479 to line 464. A number of such pairs of coils each cooperate with one of a group of contacts GC arranged in series. One or more of these contacts may be plugged in series with minor and major group control magnets MI and MA. As long as the contacts GC are held closed by simultaneous energization of coils GCA and GCB, control magnet MI and associate magnets MI1, MCR and OTR remain energized to continue the normal running operation of the machine. Magnet MCR controls the continuation of tabulator operation, because it holds contacts 469 (Fig. 35) closed. The minor control circuit may be followed from line 464 (Fig. 35A) through contacts P1 and P8 closed on the initial starting resetting cycle of the machine, magnet MI, magnets MI1, MCR and OTR, contacts L10 and L9 and wire 483 to line 465. Magnet MI closes associated contacts 484 to establish a holding circuit by shunting contacts P1 and P8 with a wire 485 to line 464. During tabulating and listing cycles of the machine, the contacts GC provide a shunt circuit around contacts L10 which are opened late in each cycle to test the group control circuit. With the plug connection 486 made as shown, and switch MIS opened to select minor control the three lowermost contacts GC when closed showing minor agreement, short circuit contacts L10, the circuit running from the lower blade of contacts L10 to the lowermost contact GC, then to the third pair, plug wire 486, and wire 487 and through major control switch MCS, card lever contacts 488 and wire 489 to line 465. If the switch MCS is opened to select major control, then the minor circuit passes from the three lower contacts GC, up through the other contacts GC, plug wire 490, contacts 488 and wire 489 to line 465. Thus, if at the time contacts L9 and L10 open and the control coils have registered agreement between the two cards analyzed, the minor and major holding circuits will be sustained through contacts GC. If, at such time, any of the contacts GC have failed to remain closed, the minor holding circuit would have been broken, deenergizing relay magnets MI, MI1, OTR and the motor control relay MCR causing stopping of card feeding and initiation of total taking and reset cycles.

Normally, during the subsequent total taking cycles, closure of cam contacts P1 and P8 re-establishes the group control circuits. However, under ledger posting control it is desired that the machine be merely stopped when a group change occurs while listing. The automatic reset switch ARE and the automatic restart switch ARS are opened so that restarting is controlled by contacts 461. Then time is allowed for the ejection of one ledger sheet and the insertion of a new sheet without any need for a total and reset

cycle. Under such conditions, means must be provided to reestablish the group control circuits as contacts P7 and P8 normally do. For this purpose, there are provided a pair of contacts 491 attached to wire 485 to shunt contacts P7, P8 and contacts 484. These contacts 491 are closed by a relay B when the sector 278 (Fig. 14) is lifted to raise the platen after ejecting a ledger sheet.

Another form of ledger posting control while listing involves the printing of an offset total such as the one shown in the second line on the sample sheet in Fig. 20. For such printing control the automatic reset switch ARE is closed but line spacing is prevented between the item print 15 and total print as explained hereinafter.

When operating under listing control, an item printing operation accompanies the sensing of each card. The machine may be set for the other well known form of control named tabulating control whereby the items on a related group of cards are sensed and added together, but only the total is printed, and that occurs after the sensing of a group change. Thus, the lines of print on the ledger sheet may be produced as an incident to each item entering operation, or each line may represent a total of a plurality of items.

The items are added under control of adding magnets AM (Fig. 35) which are energized differentially by impulses controlled by the cards under the lower brushes. At the same time and under control of the same brushes, printing is controlled by energizing magnets PM. A typical adding and printing circuit may be traced from line 465 (Fig. 35A) circuit breaker contacts CBC, card lever contact 480, contact roller 481, perforation in the record card, brush LB, plug wire 492 (Fig. 35) magnet AM, and branching through contacts 493 to print magnet PM and then to line 464. In this manner, the adding magnet 40 AM and a corresponding printing magnet PM are concurrently energized through the parallel circuit traced and the number represented by the location of the perforation will be entered into an accumulator and printed on the ledger sheet under control of the printing magnet.

Totals are printed under control of the same magnets PM. An emitter E initiates total control impulses which are directed through commutator devices C set by the accumulator and then passed through printer magnets PM. Thus the typebars are set to print the total amount registered in the accumulator.

For a detailed explanation of the tabulator operation, reference may be made to the description in Patent 1,976,617.

The carriage motor M (Fig. 35A) is energized as soon as the power switch S (Fig. 35) is closed, but many of the other ledger posting electrical controls are ineffective until three arms PSa, PSb and PSc of a posting control switch P (Fig. 14) are closed.

After a sheet ejecting operation, the platen is raised and made ready for the insertion of another sheet. When in this position, sector 278 (Fig. 35A) closes a pair of contacts 292 in line with a circuit conditioning or interlock relay B. This relay is energized by a circuit from line 464, through contacts 292, wire 494, relay B, wire 495 and contacts L101 to line 465. The relay 70 attracts contacts 496 to form a holding circuit including line 464, wire 497, contacts 496, relay B, wire 495, contacts L101 and line 465. The relay B operates two pairs of contacts 498 and 499 in addition to the group control restoring con-

tacts 491 already discussed. Contacts 498 are opened to select initially high speed control rather than end of paper control. Contacts 499 are closed so that a relay R may be energized as soon as the platen is lowered. Contacts L101 open on the first listing cycle to deenergize relay B.

Assuming that the platen is raised and that a ledger sheet has just been inserted, then lever 10 275 (Fig. 13) is operated to trip arm 293 and allow sector 278 to lower the platen. As sector 278 swings down (Fig. 35A) contacts 291 are closed to make the sheet sensing brushes 182, 183 and 184 effective.

Either of the brushes 183 or 184 immediately becomes effective through a marginal hole 51 (Fig. 20) and remains effective for a length of time determined by the length of the line of perforations. As long as perforations are sensed by the high speed control brush 183, a high speed relay HSR is energized by a circuit including line 464, contacts 291, wires 500 and 501, switch PSb, wire 502, brush holding link 202, brush 183, a perforation in the ledger sheet, contact strip 194, wires 503 and 504, relay HSR, wire 505 and line 465. Relay HSR then closes associated contacts 506 to put the high speed clutch magnet HSM and the detent release magnet DRS into operation by a circuit from line 464 through contacts 291, wires 500, 501 and 508, clutch magnet HSM, detent magnet DRS, contacts 506, contacts 509 closed due to the action of relays B and MCR, contacts L101 and line 465. The energized magnet HSM then closes the clutch gear 35 224 (Fig. 11) to disk 264 to drive the platen and feed the sheet rapidly. At the same time magnet DRS (Fig. 12) pulls out the detent roller 331.

Relay HSR also operates to open a pair of contacts 507 so that the tabulator starting relay SR is prevented from operating during high speed sheet feeding.

When the ledger sheet 50 is fed far enough so that the last marginal hole passes brush 183, the brush is insulated by the sheet, relay HSR is de-energized, contacts 506 open, and magnets HSM and DRS are also deenergized to terminate the high speed feed.

While the high speed feed is operating, the line spacing feed is also operating through top control brush 182, but to no avail because ratchet gear 257 (Fig. 12) is moving faster than pawl 253. However as soon as the high speed feed stops, the line space feed takes control for the last few spacing operations to place the sheet in correct posting position. The line space control circuit runs from line 464, through contacts 291, wires 500, 501, switch PSb, wire 502, link 202, brush 182, a hole in the sheet, roller 185, contact pieces 190, 191, contact ring 192, wire 510, switch PSc, wires 511 and 512, line space magnet LM, and line 465. Magnet LM then trips the line space clutch devices, shown in Figs. 13 and 14, to feed the sheet one line space. This feeding operation brings the next marginal perforation 51 under brush 182 so that another impulse is sent through magnet LM. Thus, line spacing operation continues until the bottom hole 51 passes above brush 182 and the sheet insulates the brush as the sheet is placed in position for printing.

As brush 182 encounters marginal perforations in the ledger sheet, a relay R is energized along with the first energization of line space magnet LM. The circuit through relay R includes

line 464, contacts 291, wires 500, 501, switch PSb, wire 502, contact holder link 202, brush 182, roller 185, contact pieces 190, 191, contact ring 192, wire 510, switch PSc, wire 511, wire 512, contacts 513, relay R, contacts 499, and line 465. As soon as relay R is energized, it breaks contacts 513 and closes other contacts 514 connected therewith to form a holding circuit. The holding circuit may be traced from line 464, to contacts 291, wires 500, 501, wire 515, wire 516, contacts 514, relay R, contacts 499, and line 465. Relay R operates to close a pair of contacts 517 so that a magnet SR connected therewith may be effective to start the tabulator automatically only at a time when a ledger sheet is inserted and at the end of such operation. Contacts 499, in line with relay R, break open during the first listing cycle when control relay B is deenergized. Then relay R is also deenergized and allows contacts 517 to open preventing any operation of magnet SR during tabulating operation.

It is mentioned hereinbefore that the automatic starting relay magnet SR (Fig. 35) is effective when energized to close contacts 461 arranged in a shunt circuit around the start key contacts of the tabulator so that the machine may be automatically started as soon as the ledger posting sheet is placed in the correct printing position. Turning to the bottom of Fig. 35A, it is noted that arranged in series with starting magnet SR is a series of four contacts for controlling the time of energization of this magnet. The effect of all these contacts is to delay the energization of magnet SR until the time that the bottom marginal perforation 51 on the ledger sheet passes above the sensing brush 182, at which time the ledger sheet is in the proper posting position. As explained before, contacts 507 are opened by relay HSR so that tabulator starting cannot occur during high speed feeding. It is also noted that contacts 517 are closed by relay R so that the starting magnet SR may be energized only when the ledger sheet inserting controls are in effect. The other two contacts 249 and 318 in series with the starting magnet SR are operated by the line spacing mechanism which is the mechanism in operation at the end of the sheet inserting cycle.

It is noted hereinbefore with reference to the line spacing mechanism shown in Fig. 13 that contacts 249 are opened by the line space clutch cam 243 when the clutch is in operation and that the contacts 318 are open whenever the magnet LM is energized. The time of operation of these contacts overlap so that as long as the regular impulses are received by magnet LM, either one or the other of two contacts will be open. It is only at the time when the last marginal perforation passes above brush 182 that the brush is insulated to deenergize magnet LM, allowing contact 318 to close after which contact 249 closes when the line space clutch completes the last spacing cycle. Then the time is reached for the starting of the tabulator and magnet SR is energized over a circuit from line 464, through contacts 291, wires 500, 501, and 515, magnet SR, contacts 517, 507, 249, 318, and line 465.

During the first tabulator cycle the solenoid SS is energized to allow the punch and brush holding frame 133 to slide to a position wherein the punch plunger is in line with the marginal perforations in the ledger sheet, thus taking the sensing brushes out of line with these perforations as explained with reference to Figs. 4 and 5.

Cam contacts L-105 close momentarily to energize the solenoid early in the tabulating operation. The cam contacts operate on other successive operations, but the solenoid is effective only on the first operation after the insertion of a ledger sheet. The circuit through solenoid SS may be traced from line 464, through contacts 291, wires 500, 501, 508, and 518, solenoid SS, contacts L105, wire 519 and line 465.

10 The punch solenoid PS is energized in one of two ways according to whether the machine is set for listing or tabulating. If the machine is set for listing, cam contacts L102 are closed on every item printing cycle to control the punching of a marginal perforation in the ledger sheet in line with the printed item. Cam contacts L102 and P204 both operate during tabulating control, the former on each cycle and the latter at the end of a group when the total is printed. During tabulating operation, the record cards are fed rapidly and analyzed to control accumulation, but item printing and ledger sheet feeding operations are suspended, so that successive operations of contacts L102 and the punch solenoid PS then merely cause successive penetration of the punch plunger at the same location on the ledger sheet. If a large amount of tabulating work is to be done, and the idle operation of the punch is found objectionable, switch PSW may be raised, Fig. 35A, to break the connections between solenoid PS and contacts L102. If listed items are to exercise the sole control of posting, then the switch may be lowered to cut out the total punch control. All punching control may be disabled by swinging the switch out of contact, away from both cam contact terminals. If the machine is set for tabulating with switch PSW raised to connect contacts P204 only with solenoid PS, cam contacts P204 close only during the printing of the total which occurs at the end of a group of related record cards. The circuit through solenoid PS may be followed from line 464, through contacts 291, wires 500, 501, 508, and 518, solenoid PS, switch PSW, contacts P204 and wire 519 to line 465.

50 The line spacing magnet LM is effective not only through brush 182 to bring the ledger sheet into the initial posting position, but it is also used to space the ledger sheet as printing and punching operations take place. It is also connected to control the feeding of sheets other than ledger sheets. A lever 520 (Fig. 35A) in the tabulator is adjusted to close or open contacts 521 according to whether the tabulator is conditioned for listing or tabulating operation. These contacts are in series with the line spacing control magnet LM and arranged to call in other contacts to control the time of operation and the number of impulses carried through this magnet. Late in every listing operation, a pair of contacts L103 close to direct a line spacing impulse through magnet LM. The circuit is from line 464, through contacts 291, wire 500, contacts 521, switch OTS, contacts L103, wire 512, magnet LM, and line 465.

60 If during listing it is desired that totals be printed in an offset relation with the last printed item of the group, switch OTS is opened so that contacts 522 in parallel therewith may open to prevent passage of a spacing impulse through L103 so that the printed total is placed in line with the last item of a group as the total in line 2 of the ledger sheet shown in Fig. 20 is represented. When a group change is detected, an offset control magnet OTR is deenergized along

with the other group control magnets MI and MCR. This magnet OTR is associated with contacts 522 so that its deenergization allows these contacts to open so that the spacing operation is prevented on the last listing cycle of a group and space between item printing and total printing is eliminated.

When the tabulator is used for a tabulating form of ledger posting work, lever 520 is set to open contacts 521 so that cam contacts L103 are ineffective but other contacts are used to energize the line space magnet LM for every total printing operation, such impulse initiation being taken care of by a pair of cam contacts P202 arranged independently of the switch lever 520. These contacts close during each total printing operation to space the ledger sheet between printing operations. The circuit for total control of the line spacing magnet LM may be followed from line 464, through contacts 291, wire 500, wire 523, contacts P202, wire 524, wire 512, magnet LM, and line 465.

When the line spacing mechanism is to be used for ordinary listing and total printing operation wherein an extra space is desired between the printed total and the first item of the next group, or extra space is needed between two printed totals, lever 520 is operated to close contacts 521 and put another pair of cam contacts P203 in the circuit. The closure of these contacts P203 is effective through a circuit including a wire 525 and wire 524 to direct an impulse through line spacing magnet LM at a time after the closure of the other contacts P202 so that a double operation of the magnet LM is produced to create extra spacing between printing operations. The extra space selection controls are provided for ordinary operation other than ledger posting work. When the machine is set for posting and item listing, ejection follows immediately after the last item of a group is printed and then the total is not printed because the automatic reset switch ARE, Fig. 35, is opened to prevent the operation of the usual total printing and reset cycle as explained hereinbefore.

Devices are provided for operating the high speed feeding mechanism to eject the ledger sheet after the last item of a group is printed or after the total of a group is printed. For this purpose, a relay A is energized at the end of a series of listing cycles by the combined closure of cam contacts L104 and contacts 526 closed when the group control magnet MI is deenergized. The circuit through relay A includes line 464, contacts 291, wires 500, 501 and 515, contacts 526, contacts L104, switch TES, relay A and wire 527 to line 465. The energized relay A closes associated contacts 528 to establish a holding circuit through wire 529 connected to wire 515. Also associated with relay A is a pair of contacts 530 in series with the high speed clutch magnet HSM. Also in series with the high speed clutch magnet are the contacts L101 which close only after printing so that ejection cannot take place before the last printing operation. The high speed clutch magnet is energized over the circuit from line 464, contacts 291, wires 500, 501, and 508, magnet HSM and DRS, contacts 530, wire 531, contacts L101, and line 465.

A similar high speed ejection of the ledger sheet is caused by the closure of contacts P201 at the end of each total printing cycle during tabulating operation. The circuit through relay A runs from line 464 through contacts 291, wires 75

500, 501 and 515, contacts P201, switch 533, wire 532, relay A, and wire 527 to line 465.

The automatic ejection devices controlled by the group change mechanism may be disabled by opening the switch TES so that when totals are to be printed, ejection of the sheet will be delayed from the last list cycle to near the end of the total print cycle. Cam contacts P201 are then effective instead of contacts L104. The switch TES may be connected to the automatic reset switch ARE in the tabulator so that when ordinary automatic tabulating operation is desired, operation of the tabulator switch will automatically change the ledger posting ejection control to allow total printing. Another switch 533 arranged in series with contacts P201 may be opened to prevent ejection during total taking operation in listing or tabulating.

The machine is provided with means for sensing the passage of the end of the ledger sheet beyond the lower sensing brush 184. It then acts to energize the end of paper control relay EPR and the platen raising magnet PRM so that the sector 278 is swung to lift the platen and at the same time break contacts 291 to disable the feeding, punching and ejecting devices. The end of paper control may be called into action due to ejection of the sheet after the printing of a total or a final item, or due to the ordinary spacing of the sheet until the lower limit is reached. In any case, the sheet passes above brush 184 and permits the brush to contact with strip 194 setting up a circuit from line 464, through contacts 291, wires 500 and 501, switch PSb, wire 502, contact link 202, brush 184, contact strip 194, wire 503, eject relay HSR over one branch and contacts 498 closed during and after the first tabulating cycle and control relay EPR over another branch, and wire 505 to line 465. Relay HSR initiates a sheet ejecting operation which is followed by a platen lifting operation. Contacts 506 are closed by relay HSR and the high speed clutch magnet HSM is called into action with the result that the sheet is ejected beyond brush 182, allowing the brush to establish contact with roller 185 and thus energize line space magnet LM through connections including switch PSc and wires 511 and 512. In the meantime relay EPR closes a pair of contacts 534 in series with the platen raising magnet PRM. Also in series with this magnet are the contacts 319 which are closed by operation of the line space magnet. Therefore, the operation of platen raising follows after ejection, because the raising magnet PRM is not energized merely through closure of contacts 534 by relay EPR, but awaits closure of contacts 319 after sheet ejection. During high speed ejection, raising control contacts 319 are closed, not due to action of cam contacts L103, but due to the cooperation between brush 182 and roller 185 when the ledger sheet passes away from the platen. Then the line space magnet LM is also energized to operate plunger 317 to close contacts 319. The platen raising magnet PRM is energized over the circuit including line 464, contacts 291, wires 500, 501, 515, and 535, contacts 534, magnet PRM, contacts 319, and line 465. When energized, magnet PRM (Fig. 13) releases the platen lifting clutch so that sector 278 is operated to raise the platen. At the same time, contacts 291 are opened and contacts 292 closed. The closing of contacts 292 again energizes relay B so that it may condition various ledger posting devices in readiness for the spacing of the next ledger sheet inserted in the machine.

A means is provided to prevent ejection of a sheet before a total is printed, when a group control break and end of paper sensing coincide. The group change manifests itself by deenergization of control relay MCR which allows contacts 509 to open to prevent energization of eject clutch magnet HSM and thus holds up ejection and platen lifting until after the total is printed.

As soon as relay EPR becomes energized it opens contacts 460 (Fig. 35) to stop the tabulator while sheet ejection, platen raising, platen lowering and sheet insertion feeding take place. The tabulator is restarted by action of relay SR as explained hereinbefore. Contacts 318 in series with relay SR are closed after ejection when spacing control magnet LM is deenergized, and that occurs only when the newly inserted sheet insulates brush 182, indicating that the sheet is finally positioned. To further insure that start relay SR remains inactive until the inserted sheet is ready to receive printing impressions, contacts 249 are put in series with relay SR; and in Fig. 13 it is seen that these contacts are closed by lever 247 only when the line space clutch cam 243 is near the home position. Therefore it is apparent that relay SR starts the tabulator only at the very end of the last line space sheet inserting operation which is the operation that places the ledger sheet in printing position.

While printing operations are carried on, the indicating mechanism is operated in synchronism with the sensing of the record cards. The indicator clutch magnet ICM is held energized by the closure of cam contacts L106 during the period of tabulating operation wherein index points are sensed on the record cards. The circuit through clutch magnet ICM includes line 464, wire 536, switch PSa, magnet ICM, wire 537, contacts L106, wire 538, and line 465.

Although the friction clutch is held in constant operation during the sensing period of the cycle, it is effective only at distinct intervals under control of the circuit breaker contacts CBC which operate the indicator release magnet IRM by a series of impulses. The impulses directed to magnet IRM follow a path through line 465, contacts CBC, contacts 473, wire 539, magnet IRM, wire 540, switch PSa, wire 536 and line 464.

At the same time the indicator pin setting magnets IM are operated under control of impulses directed through the upper brushes cooperating with the group control perforations in the record card. The differentially timed impulses are directed through the upper brushes along a line of wiring including line 465, circuit breaker contacts CBC, contact roller 474, upper brush UB, plug wire 475 to plug socket 476, indicator magnet IM, wire 541, switch PSa and wire 536 to line 464. The higher order indicator magnets IM which are not connected to the upper brushes are connected to plug sockets 542 in line with cam contacts L107 which close at the zero index point to operate the indicator pin corresponding to the indication of the number "0." This is done to fill out the higher orders of the indication and prevent confusion which otherwise result when meaningless characters are exhibited in the higher orders. The circuit for the indication of zero in the higher orders includes connections through line 465, contacts CBC, contact 473, wire 539, contacts L107, plug sockets 542, plug wire 543, socket 476, magnet IM, wire 541, switch PSa, wire 536, and line 464. Although the indicator control pins are set by magnets IM on every operation of the tabulator, the indi-

cator wheels are controlled thereby only when the platen is raised as explained hereinbefore.

Photocell control of ledger sheet feeding

In Figs. 29, 30 and 36 is shown a modified form of ledger sheet sensing devices wherein two photocells 550 and 551 are influenced by rays of light directed through the marginal perforations 51 in the ledger sheet and the photocells in turn, control line spacing and high speed feeding of the sheet.

It is clear from the showing in Fig. 29 that most of the mechanism at the right end of the platen is the same when photocells are used as it is when sensing brushes are used, the differences being in the provision of supporting means for the photocells and an illuminating bulb 552, a holder 554 for a light reflecting mirror 555, and apertures and lenses 556, 557, 558 through which the light rays may be concentrated and directed on the photocells.

The platen shaft 67 instead of extending through bushing 71 and side plate 56, ends in a hub 559 on an arm 560 secured to the inside of the guide 101, Fig. 16, which is part of the frame of the platen.

Attached to side plate 56 is a base bracket 561 carrying a socket 553 for bulb 552, a standard 562 for photocells 550, 551 and lenses 557, 558, and a standard 563 for lens 556.

Fixed to the shifting punch frame 133 is the cylindrical mirror held 554 of the same diameter as platen 52. Riveted to the rear wall of the cylinder is the mirror 555 with two beveled reflecting surfaces 564 and 565 (Fig. 30).

The bushing 71 on swinging arm 68 is hollow and in line with a hole 566 in side plate 56 through which the light rays from bulb 552 may pass after going through lenses 556, 557 and 558. After the light rays pass through hole 566 and bushing 71, they are reflected upward by the mirror surfaces.

The light diverted by surface 564 passes first through a hole 567 in the periphery of cylinder 554, then through a hole 51 in the ledger sheet, and finally impinges against the light sensitive reflector element 570 in the line spacing photocell 550.

The other portion of light which is reflected by surface 565 is directed to the left (Fig. 30) through a hole 571 in cylinder 554, a hole in the ledger sheet, and then thrown against the sensitive element 572 in the high speed control photocell 551.

Holes 567 and 571 are in alignment in cylinder 554 and are positioned to coincide with the marginal perforations 51 in the ledger sheet 50 when the punch frame is moved to the right (Fig. 29) to place the punch plunger aside from the right edge of the sheet. When the frame 133 is shifted to the left so that the punch is in effective position, the imperforate part of the ledger sheet overlies the holes in the cylinder and thus cuts off the light rays.

Fastened to the base 561 is a cover 573 which prevents light from striking the photocells from any source other than the projected rays from bulb 552.

The electrical connections for photocell control

The wiring of the tabulator and the ledger posting carriage for photocell control is the same as the wiring shown and described with reference to Figs. 35 and 35A with the exception of the wiring shown in heavy lines on Fig.

36. There it is noted that bulb 552 is illuminated when switch PSc is closed, the platen lifted and relay B energized as indicated by the closure of contacts 574 in series with the bulb. The lighting circuit includes line 464, wire 575, bulb 552, wire 576, switch PSc, wire 577, contacts 574, wire 578 and line 465.

The photocells 550 and 551 are wired in parallel, each in series with an amplifying tube and an operating relay. The connection is such that the electron emission set up by light impinging on a cell is amplified and utilized to operate a relay. Photocell 550 is wired in series with an amplifier 579 and a line space relay LSR, while photocell 551 is in series with amplifier 580 and high speed relay HSR1. The entire unit is connected to the power lines 464, 465 by wires 581 and 582. The sensing devices are normally inoperative because of the darkness under the cover 573. When no sheet is present on the platen when lowered, it is immediately raised by the end of sheet sensing devices described herein-after. In the raised position, the photocell devices are ineffective because the light openings 556 and 71 (Fig. 29) are not in alignment. Action of the relays is brought about by rays of light passing through the marginal holes in the ledger sheet.

Photocell 551 is the first to be reached by a ray of light through the top marginal hole in the sheet. Then relay HSR1 is energized and contacts 506 and 507 are operated to energize magnet HSM to drive the platen, and to prevent energization of magnet SR so as to withhold tabulator operation as explained herein-before. As the platen is driven, the ledger sheet moves the marginal holes past the apertures 567 and 571.

When the last marginal perforation in the ledger sheet passes above aperture 571 (Fig. 30) control passes from photocell 551 to the line space photocell 550 operated by light through hole 567. The last few margin holes permit light rays to fall on cell 550 and related impulses are directed through the connected relay magnet LSR. This magnet then closes contacts 583 in series with the line space clutch magnet LM to form a circuit from line 464 through contacts 291 closed when the platen is down, wire 584, contacts 583, wire 585, magnet LM and line 465. An impulse is directed through the foregoing circuit each time a perforation appears at the opening 567. The resulting energization of magnet LM causes one line space movement of the ledger sheet for each impulse as explained before. When the last marginal perforation is fed past opening 567, the light rays are cut off and the sheet stops in position for posting under previously printed data. Alternate operations of printing and sheet spacing continue until the end of the sheet is reached. The passage of the end of the sheet is sensed by a contact 586 (Fig. 30) which is usually separated by the sheet from cooperating with a contact segment 587 in an insulation block 588 fastened to cylinder 554.

In the diagram (Fig. 36) it is seen that the end of paper contact 586 is wired to the high speed relay HSR1 and the end control relay EPR. The circuit closed as the end of the sheet passes contact 586 may be traced from line 464, through contact 291, wire 501, switch PSb, wire 589, segment 587, contact 586, wire 590, and then the circuit branches out; in one direction through wire 591, relay HSR1 and wire 582 to line 465, 75

and in the other direction through contacts 498; relay EPR and wire 505 to line 465. Relay HSR1 serves to initiate operation of the high speed clutch to turn the platen and eject the sheet, and the other relay EPR influences magnet PRM to lift the platen in position for the insertion of another ledger sheet.

The manual control of ledger sheet feeding

Figs. 31, 32, 33, 37, and 37A illustrate modifications in the ledger sheet feeding controls whereby manual key operated control may be exercised for regulation of sheet feeding instead of sensing brush or photocell control.

15 Two keys project through the cover plate 276 (Fig. 31) in front of the platen raising lever 275; a high speed key 592 and a line space key 593. These keys are loosely pivoted on a stud 594 fixed in frame 57 and supported by housing H.

20 A forwardly extending finger on key 592, overlies the top blade of a pair of contacts 595, so that when the upper exterior projection of the key is moved clockwise by the operator, the contacts are closed and high speed feeding is initiated. As the operator presses this key he watches the marginal line of perforations in the moving ledger sheet. When the last perforation approaches within a few spaces from the posting line, he releases the key 592 and presses key 593 for final adjustment.

25 Fixed to line space key 593 is an arm 596 with a stud 597 cooperating with an extension 598 on line space armature lever 236. When the key is pressed down and rocked in a clockwise direction, stud 597 swing up to rock lever 236 in a clockwise direction on shaft 237. This serves to release the line space clutch pawl 238 and cause line space operation just as though magnet LM had been energized. The operator presses key 593 for line spacing as often as required to shift the ledger sheet into posting position. This position may be gauged by the operator as he watches the last marginal perforation go into line with the punch. Then he operates the key once more to move the sheet so that the last perforation is one line space above the punch.

30 The key 593 has another function besides that of controlling line spacing. It is used to close contacts 599 to start the tabulator after the ledger sheet is properly positioned. The operator remains in touch with key 593 after the last line space operation. Then he merely operates it in the reverse direction by pressing a finger against the front part of the key. Counterclockwise rocking of the key causes a projection 600 thereon to lift the lower blade of contacts 599 to close the contacts.

35 Both pairs of contacts 595 and 599 are mounted on a boss 601 on frame 57 but separated therefrom by insulation spacers 602.

40 Key 593 is restored to, and held in, normal position by a detent arm 603 loosely mounted on shaft 237 and carrying a stud 604 which cooperates with a V shaped notch formed in the rear edge of the key. A spring 605 pulls the arm 603 to press the stud into the notch and against the wall of the notch to restore the key when it is moved in either direction out of normal position.

45 The passage of the end of the ledger sheet is sensed by a contact blade 606 (Fig. 33) mounted on an insulation bracket 608 and sprung towards

a contact tube 607 imbedded in insulation disk 131c.

The operations initiated by the manual closure of contacts 595 and 599, the tripping of line space clutch pawl 236 and the closure of contact 806 may be described further with reference to the wiring diagram in Figs. 37 and 37A.

The electrical connections for manual control of the posting feed

The operations of the electrical devices in the tabulator and posting carriage for manual control are the same as described with reference to Figs. 35 and 35A except as pointed out herein-after with reference to Figs. 37 and 37A.

Assuming that the platen is in raised position and that a sheet has been inserted by the operator, he then operates the platen lowering lever 275 (Fig. 31) to operate the clutch for swinging the platen into the lowered printing position.

After the platen is in printing position, the operator then depresses the high speed key 592 to close contacts 595 in series with the high speed clutch magnet HSM and the detent release solenoid DRS. The circuit through these connections may be traced on the diagram in Fig. 37A through line 464, contacts 291, wire 501, switch PSb, wire 508, magnet HSM, solenoid DRS, contacts 595, and wire 609 to line 465.

As the operator holds his finger on key 592, he watches the marginal perforations in the ledger sheet as it is moved at high speed around the platen. When the end of the line of perforations comes into sight around the front part of the platen, he instantly withdraws his finger to allow contacts 595 to open.

The operator then turns to line space key 593 (Fig. 31) which he depresses the required number of times to bring the last marginal perforation on the ledger sheet one space above the perforating position. Each time the key 593 is depressed, it rocks the armature lever 236 controlling the line spacing clutch as explained hereinbefore. The clutch is connected to move the platen through one space for each operation. This operation has the same effect as if an impulse had been directed through line spacing magnet LM. Line spacing operation is caused by a depression of key 593 in a clockwise direction (Fig. 31) but after the sheet is properly positioned, the operator, maintaining in touch with key 593, moves it in the opposite direction to start the tabulator in operation.

A counterclockwise motion of key 593 (Fig. 31) serves to lift projection 600 to close contacts 599. At the top of Fig. 37 it is noted that contacts 599 are arranged as a shunt closure around the start key contacts ST. Wire 610, contacts 599 and wire 611 comprise the shunt circuit. The tabulator then feeds and senses the perforated record cards and controls the printing of data on the ledger sheet.

Before the tabulator is started, the punch frame is moved over to the right automatically as the platen is lowered, so that the operator may observe the positions of the marginal perforations on the ledger sheet.

Early in the first tabulating cycle, contacts L103 close to energize the punch frame release solenoid SS so that the punch plunger is moved over to the left in line with the marginal perforations on the ledger sheet.

During listing, the ledger sheet is spaced one

line for each printing operation by means of the closure of contacts L103. A total printing operation at such time involves the closure of the two contacts P202 and P203 to cause a double spacing operation of line space magnet LM, as explained hereinbefore. The operation of the total offset contacts 522 result in disabling line spacing in order to print a total in line with an item as already explained.

10 During tabulating operation, when only totals are printed on the ledger sheet, the line space magnet LM is energized by the closure of contacts P202.

15 Along with the printing, during listing and tabulating, there are also perforating devices cooperating with the ledger sheet to punch the marginal perforations, one perforation for each line of printing. Punching operation is caused by the energization of the punch solenoid PS, due to the closure of contacts L102 or P204 during listing or tabulating respectively.

20 Printing operations continue as long as record cards of the same group are being fed. However, as soon as a group change is sensed, the group control relay MI1 is deenergized to permit the closure of contacts 526 and energization of the relay A which controls ejection of the sheet. Contacts L104 close late in the last listing cycle of a group to energize relay A over a circuit including line 464, contacts 291, wire 501, switch PSb, wire 515, contact 526, contacts L104, switch TES, relay A, wire 527, and line 465.

25 If the end of the sheet is reached before a group change occurs, operation of the machine is stopped when the end of the sheet passes above contact blade 606 allowing it to contact cylinder 607 and pass current through relay EPR which then opens contacts 460, Fig. 37, to stop card feeding and printing. The operator then 30 manipulates key 592, Fig. 37A, to close contacts 595 which are arranged in shunt around automatic ejection contacts 530 and in series with high speed feed magnet HSM which then becomes effective to initiate ejection of the sheet.

35 If it is desired that total printing take place before ejection of the ledger sheet, switch TES is opened to disable connections for energizing relay A with listing operation and enable it for control by contacts P201 closed late in a total 40 printing operation. The closure of contacts P201 is ineffective for ejection control when a progressive total is printed at the top of a sheet, at which time contacts 630 in series with contacts P201 are opened as explained more fully 45 hereinafter.

50 Another switch TPS1 is arranged in series with the punch control contacts P204 for the purpose of disabling punch operation during total printing. The two switches TES and TPS1 may be connected together with the total printing control switch TPS (Fig. 37) in the tabulator so that all three are operated at once. When total printing is selected, switch TPS1 is closed to select punching therewith and switch TES is opened to prevent ejection before total printing.

55 Relay A closes contacts 530 in series with the high speed clutch magnet HSM in order to turn the platen and eject the ledger sheet.

60 As automatic ejection takes place upon a group change, the end of the ledger sheet passes between contacts 606 and 607 allowing closure thereof and energization of the end sensing relay EPR. The circuit through relay EPR may be traced from line 464 through contacts 291, wire 501, switch PSb, contact cylinder 607, con-

fact blade 606, wire 503, relay EPR, wire 505, and line 465. The relay EPR then opens contacts 460 (Fig. 37) arranged in series with the stop key contacts SP in the tabulator to stop card feeding and printing operations of the machine. At the same time, the relay EPR closes contacts 612 (Fig. 37A) in series with the relay SR' for initiating lifting the platen. Other contacts 613 are arranged in series with contacts 612 and relay SR', and these contacts are also closed by relay A because at that time relay A is energized, due to the group change which initiated the ejection movement of the ledger sheet past the contacts 606 and 607. The energized relay SR' closes associated contacts 614 which are arranged in series with the platen raising magnet PRM. Thus, through the operation of the connections mentioned, the platen is lifted in readiness for the insertion of a ledger sheet after ejection of the previously printed sheet.

Relay SR does not control restarting in the manually controlled form of the posting devices. Instead, restarting is initiated by operation of key 593 and closure of contacts 599 which are in shunt with the start key contacts ST as explained hereinbefore.

The indicating devices function as described hereinbefore to reveal the group number of the next group of cards to be sensed by the tabulator.

There are times when it is desirable to print a total on the ledger sheet without clearing the accumulator from which the total is printed. The need for such an operation may arise when the end of a ledger sheet is reached before a complete group of items is recorded thereon. The new ledger sheet which is inserted to record the remaining items should have recorded thereon a progressive total, summing up the items on the other ledger sheet. Such progressive total printing operations are caused by depression of key PT (Fig. 37A) associated with the ledger posting carriage devices. When key PT is depressed, it closes two pairs of contacts 615 and 616. Contacts 616 are arranged in the shunt circuit including wires 617 and 618 connected around the tabulator reset contacts RK (Fig. 37). These contacts control the initiation of resetting and total printing by energizing the reset motor RM and the zeroizing control relay ZBR.

The zeroizing part of the reset cycle is prevented by the closure of contacts 615 and energization of the progressive total relay PTR. The circuit through relay PTR runs from line 464 through wire 619, contacts 615, magnet PTR, contacts P205 normally closed, and wire 620 to line 465. The relay PTR sets up a holding circuit through wire 621 and associated contacts 622 closed when the relay is energized. The relay also operates to open contacts 623 connected in series with the line spacing control contacts P202. This is done so that the ledger sheet is not spaced a double line space due to the closure of P202, but merely a single space when contacts P203 close after the printing of the progressive total.

The relay PTR operates two other pairs of contacts 623 and 624 (Fig. 37) connected in the tabulator devices to control progressive total operation. Contacts 623 are opened to counteract the closing of contacts 625 by the zero button relay ZBR. These contacts 625, when closed by operation of the resetting devices, usually result in an energization of zero button magnet ZB. This magnet ZB control the clutching of the accumulator reset shaft to a resetting drive

shaft. However, with contacts 623 open to prevent the completion of a circuit through magnet ZB, resetting is prevented and a total may be printed without clearing the amount from the accumulator.

At the same time that it is desired to prevent resetting, total printing is desired and is brought about by closure of contacts 624. These contacts are arranged in shunt around a pair of contacts 626 which are ordinarily closed due to the action of the total control magnet TC which action is disturbed by the opening of contacts 623. Closure of contacts 624 completes the circuit through the total printing relay TPR which governs the opening of contacts 493 and the closing of contacts 627 to connect the print magnets PM to the total reading commutator devices C and impulse emitter E.

Ordinarily the operation of total printing causes an ejection of the ledger sheet due to the closing of contacts P201 (Fig. 37A) and energization of the eject initiating relay A, but when printing a progressive total at the head of a ledger sheet, it is desired that the sheet remain in the machine ready for further printing operation. The prevention of an eject operation along with progressive total printing is brought about by the energization of a non-eject relay NER whenever contacts 292 close as the platen is raised. The relay NER is maintained energized until listing operation is started. The circuit through relay NER may be traced from line 464, through contact 292, wire 628, relay NER, contacts L108 and wire 620 to line 465. The relay closes associated contacts 629 to form a holding circuit which is maintained by contacts L108 until listing is started.

Relay NER opens contacts 630 arranged in series with contacts P201 in order to prevent energization of relay A and consequent ejection operation. As soon as listing operation is resumed, relay NER is deenergized by the opening of contacts L108 and contacts 630 again close to condition the devices in readiness for ejection as an incident to a group change or the printing of an ordinary clearing total.

While there is disclosed the fundamental novel features of the invention as applied to three forms, it will be understood that various omissions, substitutions and changes in the forms and details of the devices illustrated and in their operation may be made by those skilled in the art without departing from the spirit of the invention. It is the intention therefore to be limited only as indicated by the scope of the following claims.

What is claimed is as follows:

1. In a machine controlled by record cards arranged in groups, means under control of said cards for printing on a sheet, a movable platen for supporting said sheet, means for moving said platen away from said printing means and back again, devices for controlling said platen moving means, means for detecting when there is a change in card groups, intermediate instrumentalities under control of detecting means and activated upon a change in card groups, means under control of said instrumentalities for effecting operation of said controlling devices for initiating operation of said platen moving means to move the platen away from the printing means, and means for initiating operation of said moving means to move the platen back near the printing means.
2. In a machine for printing a sheet, means for

feeding said sheet, means for controlling said feeding means for ejecting said sheet, a movable platen for supporting said sheet, means for moving said platen away from a normal printing position to receive a new sheet and then moving it back again, means for sensing the passage of the end of the ejected sheet, and means under control of said sensing means for initiating operation of said platen moving means to move the platen away from the printing position.

3. In a machine for printing a sheet, a platen around which said sheet is fed, means for swinging said platen away from printing position to receive a new sheet and then back again, separate devices for initiating operation of the swinging means to swing the platen away from the printing position and back to the printing position, platen drive gearing connected to the platen but normally free to turn when the platen is swung, a latch for engaging the gearing to hold it so that the platen is turned to feed the sheet for a heading space when the platen is swung, and manipulative devices for controlling the time of engagement of said latch and the size of the heading space.

4. In a card controlled printing and indicating device, means for sensing number designations on cards, means for moving the cards relative to said sensing means, a disk, means for rotating said disk in synchronism with the movement of the cards, a series of pins on said disk, means under control of said sensing means for operating the pin corresponding to the number designation sensed, an indicating wheel, a stop pawl on the wheel, a platen for supporting a sheet at a normal print receiving position, means for moving said platen near and away from said normal print position, and means under control of said platen moving means for turning said indicator wheel until said pawl engages said pin to indicate the card number.

5. In a machine for controlling the feeding of a sheet according to the number of recording operations impressed thereon and denoted by feed controlling indicia on said sheet, means for sensing said indicia when reinserting said sheet, a member for supporting and feeding said sheet, means under control of said sensing means for rapidly operating said member for feeding said sheet to an approximate operation receiving position, a second sensing means stationed next to the first mentioned sensing means in the direction of feed of said sheet, and means under control of said second sensing means to operate said member to slowly space said sheet to the exact operation receiving position.

6. In a machine for printing items on a sheet with a feed control perforation in said sheet for each item printed, said perforations being arranged in succession in a line, a sensing brush for establishing contact through said perforations when said sheet is inserted, means for supporting and feeding said sheet, sheet feeding means controlled by said brush for operating said supporting means for feeding said sheet rapidly until the last perforation passes the brush, a second sensing brush for contacting through said perforations after they pass the first brush, and sheet spacing means for operating said feeding means as controlled by said second brush to position said sheet so that the next item printed is placed directly under the previously printed item.

7. In a machine for printing a sheet bearing a line of marginal feed control perforations which were punched in said sheet as printing pro-

gressed, a sheet feeding means, a brush for sensing said perforations, means under control of said brush for controlling said feeding means to insert said sheet short of the point to which printing has progressed, a line spacing device cooperating with said feeding means, a second brush for sensing said perforations after they pass under the first mentioned brush, and means under control of said second brush for controlling said spacing device to space said sheet one line beyond the point to which printing has progressed, a third sensing brush for detecting the passage of the end of the sheet when the end of the printed area approaches the bottom of the sheet, and means under control of said third brush for operating said feeding means to eject the sheet.

8. In a machine for printing a sheet, electrically controlled means for feeding said sheet, normally closed contacts connected to said feeding means for control thereover, a movable platen for supporting said sheet, means for moving said platen away from a normal effective position and then back again, and means under control of said platen moving means for opening said contacts to disable said feeding means when the platen is moved away from the normal position.

9. In a machine for printing a sheet, a platen for supporting said sheet, a movable frame for said platen for holding it in or away from a normal position, a driving means, a clutch between said frame and said driving means, means for initiating operation of said clutch including a normally effective clutch disengaging member, means for disconnecting said clutch after one-half cycle of operation which half cycle moved the platen away from said normal position, other means for operating said last mentioned means for initiating further operation of said clutch, said clutch disengaging member disconnecting said clutch after another half cycle of operation which half cycle moved the platen back in said normal position.

10. In a machine for printing lines of data on a sheet which bears a number of feed control indicia placed thereon in succession from a fixed position and corresponding to the number of lines of data on the sheet, a platen for holding said sheet, a feeding means for moving said platen, a pair of means for sensing said indicia successively, means under control of one of said sensing means for operating said feeding means to feed the sheet rapidly so that the last placed feed control indicium is moved directly within a few line spaces of the indicia placing position, a line space feeding means for moving said platen, and means under control of the second one of said sensing means for operating said space feeding means for shifting said sheet line by line until said last indicium is one line space beyond the indicia placing position, thereby bringing the sheet in position to receive print on a line directly under the last line of print.

11. In a machine for printing lines of data on a sheet which bears a marginal line of feed control indicia with one indicium for each line of print, means for sensing said indicia when the sheet is inserted, a sheet feeding means, means under control of said sensing means for operating said feeding means to feed said sheet continuously as long as indicia are sensed, a second sensing means for sensing said indicia after they pass the first mentioned sensing means, a line spacing means for operating said feeding means, and means under control of said second sensing means for operating said spacing means to posi-

tion said sheet line by line so that the new print receiving position of the sheet is one line below the last previously printed line.

12. In a machine for printing lines of data on a sheet which bears a number of feed control indicia corresponding to the number of lines of data on the sheet, a driving means, a sheet feeding means, a clutch for connecting said feeding means to the driving means, a relay for controlling the operation of said clutch, controls including an indicia sensing means for energizing said relay as long as said sensing means detects passing indicia as said sheet is inserted, a line spacing means for operating said feeding means, a clutch for connecting said spacing means to the driving means, a magnet for controlling the operation of said spacing clutch, and other controls including a second indicia sensing means for sensing said indicia after they pass the first mentioned sensing means and for energizing said magnet to operate the related clutch for sheet spacing operations as often as the second sensing means detects an indicium, thereby feeding the sheet rapidly to an approximate print receiving position followed by spacing to an exact print receiving position to receive print on a line directly under the last line of print.

13. In a machine for printing lines of data on a ledger sheet which bears a number of feed control indicia corresponding to the number of lines of data on the sheet, means for sensing said indicia, sheet feeding devices, a high speed feeding means and a line spacing means for operating said feeding devices, means under control of said sensing means for operating said feeding means and line spacing means in succession, the high speed feeding means acting first to move the sheet to an approximate position followed by operation of the spacing means to move the sheet line by line for inserting said sheet to a position wherein printing can be resumed to follow previously printed lines of data, means for controlling repeated operation of said line spacing means as printing progresses, means for detecting the approach of the end of the sheet near the printing position as printing progresses, and means under control of said detecting means for controlling operation of said high speed feeding means to eject the sheet after a line is printed near the bottom of the sheet.

14. In a record controlled machine for printing the data of the records on a record sheet, said sheet bearing a number of feed control indicia corresponding to the number of lines of data on the sheet, said sheet being reinserted for resumption of printing, means for sensing said indicia, a feeding means, means under control of said sensing means for operating said feeding means to feed said sheet directly to an approximate print resuming position when said sheet is reinserted, other means for sensing said indicia after they pass the first mentioned sensing means, a line spacing means for operating said feeding means, means under control of said other sensing means for controlling said spacing means for line spacing said sheet into exact print resuming position, and means under control of said feed operating means and spacing means for automatically initiating printing operation when the sheet is properly positioned.

15. In a machine for printing on a record sheet bearing feed control indicia denoting the progress of printing, a printing means, a platen and cooperating holding means for supporting said sheet near the printing means, automatic and manipu-

lative means for controlling movement of said platen bodily away from and back to the printing means, means under control of said automatic controlling means for moving said platen away from the printing means into a position wherein the insertion of a new sheet is facilitated, said moving means also serving under control of said manipulative controlling means for moving said platen back again near the printing means, sheet feeding devices cooperating with said platen to feed the sheet, means for operating said feeding devices, means for sensing said feed control indicia, devices controlled by said sensing means for controlling said operating means to feed the sheet to bring a predetermined position thereon below the last control indicium in print receiving position, and means under control of said platen moving means and the feed controlling devices for automatically initiating operation of said printing means after the platen is back near the printing means and after the sheet feed operation is terminated with the sheet in said predetermined position.

16. In a machine for printing on a sheet bearing feed control indicia for denoting the progress of printing on the sheet, a platen upon which said sheet is supported, means for moving said platen away from a normal print receiving position to facilitate insertion of a sheet, said means also serving to move the platen back again to normal position, means for controlling operation of said moving means, means for sensing said indicia, sheet feeding devices for operating said platen, means under control of said sensing means for operating said feeding devices for feeding said sheet, and means under control of said platen moving means for rendering said sensing means ineffective when the platen is away from the normal print receiving position.

17. In a machine for printing lines of data on a sheet bearing a line of feed control indicia corresponding to the number of lines of data on the sheet, sheet feeding devices, means for sensing said indicia, means under control of said sensing means for operating said devices to feed the sheet into a position wherein printing may be resumed on said sheet, means for placing additional indicia in said line of indicia on said sheet, means for operating said indicia placing means, as printing progresses, a common holder for said sensing means and said indicia placing means, and means for moving said holder to position either means thereon in effective position in alignment with said line of feed control indicia.

18. In a printing machine for posting lines of printed data on a ledger sheet with a line of feed control perforations, there being one control perforation for each line of print, means for sensing said perforations, a sheet feeding means, means under control of said sensing means for operating said feeding means to feed the sheet and bring it near print receiving position, other means for sensing said perforations after they pass the first mentioned sensing means, a line space feeding means for operating the first mentioned feeding means, and means under control of said other sensing means for operating said line space feeding means to shift the sheet into position to be printed upon directly under the last line of print.

19. In a machine for printing items on a ledger sheet having a line of feed control perforations, one perforation for each item of printing, brush devices for sensing said perforations,

sheet feeding means, means under control of said brush devices for operating said feeding means to bring the sheet to an unprinted print receiving position, a punch, means for operating said punch to extend said line of feed control perforations by cutting an additional perforation for each item printed, holding means in which said brush and said punch are mounted, and means for positioning said holding means in either of two lateral positions with respect to said line of perforations to shift said brush and said punch so that either one is in alignment with said line of perforations.

20. In a machine for printing on a sheet which has a heading space and bears a series of feed control indicia denoting the extent of printing on the sheet, means for sensing said indicia, a platen for holding said sheet, sheet feeding means for advancing said platen, means under control of said sensing means when sensing said series of indicia for operating said feeding means to advance the sheet to a position to receive printing directly under previous printing, means for moving the platen to and away from a normal print receiving position, and means under

control of said moving means when said platen is moved to the normal position for spacing said sheet an initial heading space to bring the first of said indicia into cooperation with said sensing means.

5 21. In a machine for printing on a sheet having feed control perforations revealing the extent of previous printing operations thereon, a movable platen for supporting said sheet, means 10 for moving said platen near and away from a print receiving position, brush devices situated within the periphery of the platen and cooperating with a stationary contact strip beyond the periphery of the platen for sensing said sheet for 15 said perforations, a holder upon which said brush devices are mounted, sheet feeding means controlled by said brushes to feed the sheet an extent determined by the perforations and the extent of previous printing, and means for automatically moving said brush devices on said holder to withdraw said devices from said contact strip when said moving means moves the platen 20 away from the print receiving position.
